SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

CALL-DISTRIBUTING SYSTEM.

1,386,749.

Specification of Letters Patent.

Patented Aug. 9, 1921.

Refiling of abandoned application Serial No. 107,090, filed July 1, 1916. This application filed April 14, 1919. Serial No. 290,065.

To all whom it may concern:

Be it known that I, SAMUEL B. WILLIAMS, Jr., a citizen of the United States, residing at Brooklyn, in the county of Kings and State of New York, have invented certain new and useful Improvements in Call-Distributing Systems, of which the following is a full, clear, concise, and exact description.

This invention relates to telephone exchange systems, and more particularly to systems of the type employing automatic switches for distributing calls to the connecting circuits of operators' positions.

The present invention is a division of that disclosed and originally claimed in applicant's case, Serial No. 107,090, filed July 1, 1916.

The present invention is shown in a telephone system in which calling subscribers' lines are distributed to an operator's connecting circuit through the agency of one or more automatic switches; in which traffic is distributed in such a way as to keep the operators' positions uniformly busy; in which the calls are extended to operators' positions that are at that time unengaged and diverted from those positions that are busy; and in which each calling line is extended to only one of the operators' positions that may at the time be ready to receive a call.

The object of the present invention is to provide a registering device associated with an operator's position which is effective on the extension of a call to count or charge the service given.

Other objects to which this invention is directed and which are attained in the system herein disclosed, will appear in connection with the detailed description that follows.

The preferred embodiment of the system of the invention is illustrated in the accompanying diagrammatic drawings, in which Figure 1 shows two groups of lines with two line finder switches for making connection therewith, together with the associated circuits and apparatus through the medium of which the lines control the switches; Fig. 2 shows one finder circuit complete, and enough of two other finder circuits to illustrate the relationship between them; Fig. 3 shows two cord selector switches of one frame with their associated selection con-

trolling apparatus and circuits, together with similar apparatus and circuits for the cord selector switches (not shown) of another frame; Fig. 4 shows the position apparatus and circuits of one operator's position, with enough of the position apparatus of another position to illustrate the interrelation of the two; and Fig. 5 shows one connecting cord circuit complete, together with certain inter-related parts of other cord circuits located on the same operator's position, also one of the called lines with which the cord circuit may be connected. The figures taken together, and arranged side by side in the order indicated by the lines that extend to the margins of the sheets, illustrate as much of a complete organization as is necessary to gain an understanding of the construction and mode of operation of the system.

Two telephone lines are indicated in each of the two groups shown in Fig. 1, it being understood that each group may comprise a large number of such lines. The practice is to give the finder switch brushes access to the terminals of five hundred lines, these lines being arranged in ten groups of fifty lines each. Each of the lines has associated with it at the central office a line relay 12, a cut-off relay 11 and, if it is a message-rate line, a connection register 164. Each line is also provided with one or more spring jacks 14 by means of which connection may be made with the line when it is a called line. The lines represented as calling lines in Fig. 1 and the line shown as a called line in Fig. 5 may be lines of the same sort, similarly equipped and located at the same exchange; or the lines may be located at different offices. In the present instance, the called line shown in Fig. 5 is indicated as being provided with connections by means of which it may have control over finder switch mechanism in the manner illustrated in connection with the lines of Fig. 1. Each group of lines, LG and LG', has associated with it certain group apparatus consisting of two relays 19 and 24, and a timing sequence switch 100. There is also provided apparatus common to all of the line groups, comprising the relays 22, 23 and 33.

The groups of lines have access to groups of connecting circuits through the medium of finder circuits F, F', and F'', which termi-

nate upon the brushes of pairs of finder switches of which two sets, LF and CS and LF' and CS', are shown. Each of the groups of connecting circuits is associated 5 with a particular operator's position, of which the apparatus of one is shown at O and the apparatus of the other is partially shown at O'. In the particular system illustrated, it is the practice to provide each operator's position with twenty connecting 10 circuits extending to multiplied groups of terminals upon the cord selector switches, and to give the brushes of each cord selector switch access to the terminals of twenty-five 15 such groups of connecting circuits. But one of the connecting circuits is shown complete, the other connecting circuits in the associated group and in the other groups being assumed to be similarly organized and connected. The multiple connections of the connecting circuit with the terminals of the cord selector switches are shown in the case 20 of the connecting circuit that is completely illustrated; and in like manner the multiple 25 connections of the telephone line with the terminals of the line finder switches are shown in the case of the line that extends from station A'. The multiple connections that exist between corresponding sets of 30 switch terminals for the other connecting circuits and telephone lines are omitted to avoid confusing the drawing.

A number of groups of cord selector switches like the group illustrated in Fig. 3 35 may have access to the same groups of connecting circuits and their corresponding operators' positions. This is indicated in Fig. 3. Each of the groups of cord selector switches has associated with it certain selection controlling apparatus, that associated 40 with the cord selector switches shown in Fig. 3 appearing under the caption "Frame 2," and that associated with the cord selector switches of the other group that is not 45 shown appearing under the caption "Frame 1." The selection controlling apparatus for each frame or group of cord selector switches comprises a set of relays 77, 93 and 94 for each group, CG, CG', to which the cord selector has access, and a group of relays 54, 50 55, 61 and 63, common to all of the first mentioned groups.

As the line finder switches LF and LF', and the cord selector switches CS and CS' 55 in themselves are not novel, they are shown merely diagrammatically. These switches may be substantially like the switch illustrated and described in the patent to James L. McQuarrie, No. 1,177,044, issued March 60 28, 1916. The line finder and cord selector switches are alike in all substantial respects. Each comprises a longitudinally movable 65 shaft 1 carrying as many sets of brushes 2 as there are groups of stationary terminals to be engaged. To move the shaft up, an

extension at the lower end of the shaft is brought into engagement with the constantly rotating power member 3 by means of an idler wheel operated by the up-drive magnet 32; and to move the shaft down, the extension is brought into engagement with the power member 4 by means of an idler wheel operated by the down-drive magnet 62.

Normally the brushes of each of the sets 2 are held apart so as to clear the associated 75 terminals by means of a separating cam 5 located between the innermost brushes of the set. The cam 5 is rotatably mounted, and when rotated in one direction, releases the brushes and permits them to engage the associated terminals. The tripping or releasing of the brushes is controlled by a number 80 of trip-magnets 16, 17. Each of these when energized rotates an associated trip rod 6 that extends transversely to the switch shafts 85 1 and carries as many tripping yokes 7 as there are finder switches in the group. The trip rod, in rotating, brings all of its tripping yokes 7 into position to operate the brush controlling cams 5 of the corresponding 90 sets of brushes on all of the switches, so that which ever of the finder switches is caused to move up has that set of brushes tripped that corresponds with the particular trip magnet 16, 17, that is at the time energized. When the finder switch that has been in use is returned to its normal position, any of the associated controlling cams 5 that has been tripped is engaged and rotated in a reverse direction to separate its 100 switch springs again and thus render them inactive.

Each of the line finder and cord selector switches has associated with it a commutator 8 which comprises a number of stationary commutator segments and a set of movable brushes carried at the top of the switch shaft 1 and co-operating with the stationary segments. This commutator serves to make and break a number of controlling circuits 105 in the various stages of the upward movement of the switch shaft.

For controlling the circuits of the organization, there are employed a number of sequence switches which are shown at different 115 points and are designated 100, 200, 300, 400 and 500 respectively. These sequence switches may be of the type disclosed in Patent 1,127,808 issued February 9, 1915, to Reynolds and Baldwin. Each consists of 120 an electromagnetically controlled motor or driving mechanism and a number of associated switch cams. The switch cams associated with each of the sequence switches 100 are designated 101 to 103 inclusive; those associated with each of the sequence switches 200 are designated 201 to 222 inclusive; those associated with each of the sequence switches 300 are designated 301 to 310 inclusive; those associated with each of 125 130

the sequence switches 400 are designated 401 to 416 inclusive; and those associated with each of the sequence switches 500 are designated 501 to 521 inclusive. To each of the 5 contacts associated with the various sequence switch cams are applied certain numerals. Those numerals in the case of the cams 101, 201, 301, 401 and 501 indicate the only positions of the associated sequence switch in 10 which these particular contacts are open; the numerals applied to all of the other contacts of each sequence switch indicate the only positions of the particular associated switch in which the associated contacts are 15 closed.

The sequence switches 100 merely act as timing switches and have only one resting position. The resting positions of the other 20 sequence switches, and the stages of operation with which these positions are associated, are as follows:

Sequence switch 200.

1. Normal.
2. Awaiting starting circuit.
3. Awaiting starting circuit release.
4. Hunting calling line.
5. Awaiting preceding finder circuit.
6. Awaiting operator's selecting circuit.
7. Awaiting operator's selecting circuit.
8. Releasing operator's selecting circuit.
9. Hunting cord circuit.
14. Talking.
15. Line finder at tell-tale.
16. Cord selector at tell-tale line finder returned.
17. Cord selector returned.

Sequence switch 300.

1. Awaiting a call.
4. Position vacant.
17. Position busy.

Sequence switch 400.

1. Normal.
7. Listening in.
15. Listening out.

Sequence switch 500.

1. Normal.
2. Awaiting listening key sequence switch.
4. }
5. }
7. }
8. Selective ringing operations.
10. }
11. }
13. Ringing called line.
16. Awaiting supervisory relay.
17. Talking.

In outline, the operation of the system in the embodiment disclosed is as follows: When a subscriber calls, he causes the closing of a starting circuit that is common to 65 a number of line finder switches and also

causes the energization of a trip magnet corresponding to the group of lines in which his line is located. The finder switches each have as many sets of brushes as there are groups of lines. The closing of the starting 70 circuit causes a preselected one of the finder switches to move its brushes, and the energization of the trip magnet makes active the set of brushes corresponding with the group in which the calling line is located. The apparatus which brings about the energization of the trip magnet operates to prevent temporarily the trip magnets of other groups of lines from being energized by calls that may at the time be initiated in the other groups. 80

As soon as the brushes of the finder switch are tripped, another finder switch is brought into operative relation with the starting circuit, and then the starting circuit is released and made available for the use of calling 85 lines in groups other than the group in which the first mentioned calling line is located. That group is deprived of control over the starting circuit until after the finder switch has connected with the terminals of the calling line. The object of this is to prevent the same calling line from starting a second finder switch in the interval before the calling line is found.

When the finder switch brushes complete 95 connection with the terminals of the calling line, the finder circuit operates certain apparatus that determines to which of a number of operators' positions the connection of the calling line shall be extended. The selection is effected through the medium of 100 selection controlling apparatus that is common to the cord selector switches upon which the finder circuits terminates, and to the operators' positions to which these cord 105 selector switches are designed to extend calls. When a finder circuit is ready to extend a call, it first causes all of the operators' positions that are idle or awaiting a call to indicate their receptive condition by 110 operating corresponding switch parts upon the common selection controlling apparatus. The selection controlling apparatus responds by preparing a path for the energization of a cord selector tripping magnet 115 corresponding with the first operator's position in the series that is ready to receive a call. The finder circuit that is extending the call then sends a tripping impulse over the path thus prepared. When the tripping 120 magnet operates, the movement of the cord selector switch is started. At the outset of the movement the set of brushes is tripped that corresponds with the preselected operator's position, and immediately thereafter 125 the common selection controlling apparatus is released and made available for determining the selection of other operators' positions by other cord selectors switches and finder circuits.

After the set of cord selector brushes has been tripped, the brush shaft continues its upward movement, successively engaging the terminals of the connecting circuits located at the operator's position that has been selected, and stops upon the terminals of the first connecting circuit encountered that is idle and available for use.

Prior to this, and at the instant that the 10 operator's position is selected and the corresponding trip magnet energized, a tone is produced in the operator's telephone receiver which notifies her that her position has been selected and that a call is coming. 15 At the same instant, the listening-in keys associated with all of the connecting cords of the position are rendered inoperative so that the operator cannot interfere with the coming call by listening in on a cord circuit 20 after the position has been selected and before the call arrives.

When the cord selector switch stops on the terminals of the selected connecting circuit, it lights a lamp associated with that 25 circuit on the operator's position and at the same time causes the tone in the operator's telephone receiver to cease. It also moves a sequence switch of the selected connecting circuit to bring the operator's telephone set 30 into connection with the selected circuit, and operates a relay that closes the circuit to the operator's telephone instantly and in advance of its closure by the sequence switch, thus saving time in establishing communication 35 between the calling subscriber and the operator.

When the operator has received the calling subscriber's instructions, she tests the line that is called for and, if it is free, inserts the calling plug into the line jack. 40 This act automatically disconnects the operator's telephone apparatus from the circuit; and the disconnection of the operator's telephone apparatus causes the actuation of the 45 calling cord apparatus to apply ringing current to the called subscriber's line.

While the calling line and called line are united, the operator can bring her telephone apparatus into or out of connection with the 50 circuit by pressing the listening-in key individual to the circuit or the listening-out key common to all of the circuits. In pressing a listening-in key to bring her telephone set into connection with one of the connecting circuits, the telephone set is automatically disconnected from any other connecting circuit with which it may at the time be in connection.

As long as the operator's telephone set is 60 in connection with a cord circuit, the operator may withdraw the calling plug from the spring-jack of the line into which it was first inserted and insert it into another spring-jack without disturbing the connection of the calling line with the circuit,—as

when the calling subscriber wishes connection with several different lines in succession. But if the operator withdraws the calling plug in response to the disconnect signals, without reconnecting her telephone with the 70 cord circuit, the connection is released and all of the switches return to normal. If the calling line is a message-rate line, the operator, before withdrawing the plug, presses a charge key which causes a registration 75 upon a meter associated with the line, and which also makes the calling plug ineffective to bring about the release of the connection while the charge key is depressed. Also at the instant of release, a relay acts to prevent 80 any possible reenergization of the line relay of the calling line when that relay is reconnected by the falling back of its associated cut-off relay.

The operators' positions are arranged to 85 receive incoming calls by way of several groups of finder circuits with their associated cord selector switches, and to prevent interference between simultaneous calls originating in different groups of finder 90 circuits, the arrangement being such that when the selecting apparatus of one group acts to select a particular operator's position, that position is made inaccessible to the selecting apparatus and finder circuits 95 of another group. The different operators' positions are also so inter-related that the positions are kept equally busy, this being accomplished by rendering each position inaccessible to incoming calls after it has received a call or after the operator has supervised 100 an existing connection, and restoring its accessibility only when all of the positions have received a call or supervised a connection. The positions are then all restored to accessibility excepting such as may at the time be attending to a call or to a connection, or have all of their cords in use, or may be out of service by reason of the operator being absent from the position. 105

The features of the operation that have been set forth in outline in the foregoing, together with other features present in the system, will be fully explained in the detailed description, that follows.

It will be assumed that the subscriber at station A initiates a call. When the telephone receiver is taken from the switchhook, a circuit is closed that extends by way of both windings of the line relay 12 and both 115 limbs of the telephone line, and is completed in the contacts of the switchhook at the subscriber's station. The flow of current in this circuit energizes the line relay 12, which, in attracting its armature, applies 125 ground to the conductor 18. This causes current to flow from battery through the winding of the relay 19, sequence switch contact 103 (10 $\frac{1}{2}$ to 1 $\frac{1}{2}$), conductor 18 and ground at the contact of the operated line relay 12. 130

The relay 19 attracts its armature and closes a circuit that extends from battery through the right-hand winding of the associated relay 24, front contact of relay 19, back contact of relay 22 and lower armature and back contact of relay 23 to ground. Relay 24 operates and closes in its left-hand front contact a circuit that extends from battery by way of the winding of the associated 5 group trip magnet 16 and the left-hand winding of the relay 24, in parallel, to the front contact of that relay, and thence by way of conductor 58, the winding of the relay 22, and the lower back contact of the 10 relay 23 to ground.

Current flowing in the circuit traced above operates the trip magnet 16 of the group in which the calling line is located, locks up the relay 24 of the associated group and operates the relay 22 common to all of the 20 groups. The trip magnet 16 rotates its associated trip rod to bring all of the yokes into position to trip the corresponding set of brushes of whichever of the line finder 25 switches is started. The group relay 24 breaks, in its left-hand back contact, the circuit of the conductor 58 to the corresponding relays 24 of the succeeding groups of the series.

30 The relay 24, in its right-hand front contact, also completes a circuit that extends from battery through the motor magnet of the sequence switch 100, and contact 102 (18 $\frac{3}{4}$ to 1 $\frac{1}{4}$) of that switch. In moving out 35 of position 1 $\frac{1}{4}$, sequence switch 100 closes its contact 101 and opens its contact 103. As contact 101 is closed in all positions excepting position 1 of the sequence switch, the switch is caused to make one complete 40 rotation; and as contact 103 of the sequence switch is open in all positions excepting positions 18 $\frac{3}{4}$ to 1 $\frac{1}{4}$, the conductor 18 is held open while the sequence switch is making its revolution and until it gets back to 45 position 1. The time required by the sequence switch to make one complete rotation is so regulated as to be greater than that occupied by the line finder switch in finding the terminals of any calling line.

50 The action, therefore, is such as to interrupt the group conductor 18, and hold it open until after the line relay 12 of the calling line has been released as a result of the finding of that line.

55 The relay 22, common to all the groups, in operating, opens in its back contact the circuit of the conductor 57, which extends serially through the back contacts of the relays 19 of the various groups. As this 60 conductor 57 is the path over which the relay 19 of any group serves to effect the initial energization of the associated relay 24 and the operation of the corresponding trip magnet, the interruption of this conductor, 65 insures the operation of only one trip mag-

net and the tripping of only one set of brushes on a started line finder switch.

The common relay 22, in its front contact, completes a circuit that extends from grounded battery through the left-hand winding of the finder circuit relay 30 (see Fig. 2), contact 206 (2) of the finder sequence switch 200, conductor 29, front contact of relay 22, through back contact of relay 23, to ground. The conductor 29 has branches 75 extending to like sequence switch cams 206 of all of the finder circuits terminating upon the line finders that have access to the calling line. But, for reasons which will hereinafter be explained, the sequence switch 80 200 of only one of these finder circuits is standing in its 2 position. In the present instance, it is assumed that this is the sequence switch of the finder circuit F.

As a result of the closure of the circuit 85 traced above, the relay 30 is energized and closes a circuit that causes the associated sequence switch 200 to move out of position 2. This circuit extends from battery through the motor magnet of the sequence switch 90 200, sequence switch contact 202 (2), right-hand front contact and armature of relay 30, sequence switch contacts 208, (18 to 14) and (2 to 7), commutator segment M of the associated cord finder switch CS', and to 95 ground by way of the brush that is in engagement with this commutator segment. Relay 30, in attracting its armatures, also closes a locking circuit for itself that extends from battery by way of the resistance 100 coil 56, sequence switch contacts 217 (2) the right-hand winding of the relay 30, sequence switch contacts 216 (2 to 4) and (2 to 9), front contact and left-hand armature of the relay 30 and armature and back contact of the relay 37 to ground.

As a result of the closure of its motor magnet circuit in the right-hand front contact of the relay 30, the sequence switch 200 moves out of position 2 and comes to rest 110 in position 3. In position 3 of the switch, a circuit is closed that extends from battery by way of the up-drive magnet 32 of the corresponding line finder switch LF', sequence switch contact 207 (3 to 4), front 115 contact and right-hand armature of relay 30, sequence switch contacts 208 (18 to 14) and (2 to 7), and to ground by way of the commutator segment M and associated brush of the corresponding cord finder CS'. The 120 energization of the up-drive magnet 32 starts the upward movement of the corresponding elevator rod with its associated sets of brushes. At the outset of the upward movement of the elevator rod, all of the brush trip levers are moved past the corresponding trip yokes. The only trip magnet that is energized in this case is the magnet 16 which corresponds with the group in which the calling line is located; and consequently, the 130

only trip yoke in position to engage a trip lever on the elevator rod is the one which controls the brushes 40, 41, 42 and 43 that are adapted to engage the terminals of that particular group of lines. This set of brushes, therefore, is released and made operative, and the other sets are held clear of their associated line terminals.

As soon as the set of brushes corresponding with the calling line is tripped, the group apparatus, by means of which the lines control the brush tripping and line finder starting operation, may be returned to its normal condition. The first step in this restoring operation is effected by the closure of a circuit which is completed by way of the K segment of the line finder commutator immediately after the brushes are tripped. This circuit extends from battery in parallel branches through the relays 23 and 33 (see Fig. 1), conductor 26, sequence switch contact 209 (2 $\frac{3}{4}$ to 3), conductor 68, and to ground by way of the K segment of the line finder commutator and its associated brush. The energization of the relay 23 interrupts, in the lower back contact of that relay, the previously described circuit that has up to this time maintained the energization of the trip magnet 16, the group relay 24 and the common starting relay 22. Relay 23, in its upper front contact, closes a locking circuit for itself and the associated relay 33 that extends by way of conductor 25 and the sequence switch contacts 210 (2 $\frac{3}{4}$ to 1) of all of the finder circuits in series to ground at a point beyond the last switch of the series.

As has already been stated, normally there is only one of the finder circuits with its sequence switch in position 2 awaiting the receipt of a call. When the call comes in, this sequence switch is immediately moved to position 3, in the manner described above. Therefore, at this stage of the operation, the sequence switches of all of the finder circuits are in position to close their contacts 210. The locking circuit for the relays 23 and 33 is, therefore, held closed until another one of the finder circuits has its sequence switch moved into position 2. This is accomplished by relay 33, which, in operating, applies a ground to conductor 28 to move the sequence switch of another finder circuit out of position 1 and into position 2, and which also applies a ground to the conductor 27 to move the sequence switch of the appropriated finder circuit out of position 3.

Assuming that the sequence switch of finder circuit F' is in position 1 and that the sequence switch of finder circuit F² is in some position between 4 and 17, that finder circuit being assumed to be in use, the operation of the relay 33 completes the following circuit: from battery, through the motor

magnet and contacts 203 (1) of the sequence switch of finder circuit F', contacts 211 (1) of the same sequence switch, contacts 211 (3 to 17) and (4 to 17) of the sequence switch 200 of finder circuit F², contacts 211 (3 to 17) and (3 to 3 $\frac{1}{2}$) of the sequence switch 200 of finder circuit F, conductor 28, lower contact and armature of the relay 33 to ground. This causes the sequence switch of finder circuit F' to move into position 2. 75

If by any chance the sequence switch of finder circuit F' should fail to be moved into the call-awaiting position 2, when the relay 33 operates, it will be moved into that position when the sequence switch of the appropriated finder circuit F moves into position 5 at a slightly later stage in the operation. The circuit by which this result would, under these circumstances, be accomplished extends from battery through the motor magnet and contact 203 (1) of the sequence switch of finder circuit F', contacts 211 (1) of that sequence switch, sequence switch contacts 211 (4 to 17) and (3 to 17) of finder circuit F² (assumed to be in use), and thence by way of contacts 222 (5 to 1) of all of the finder circuit sequence switches in series, to ground. In other words, at any time that the finder circuit sequence switches are all standing in position 1 or in position 5 and beyond, a ground is supplied by way of the 222 cams in series that moves one of the switches into position 2, and thus places the associated finder circuit in its call-awaiting condition. 95

The sequence switch of finder circuit F is moved out of position 3 by the closure of a circuit that extends from battery through the motor magnet and contacts 203 (3) of the sequence switch of that circuit, conductor 27 and upper contact and armature of relay 33 to ground. 105

As soon as the sequence switch of finder circuit F' moves into position 2, it opens its contacts 210 the circuit by way of conductor 25 which has been maintaining relays 23 and 33 energized, and these relays release their armatures. Relay 23, in releasing, reconnects to ground the circuit which extends in branches 57 and 58 through the various sets of group relays, thus again giving the groups access to the starting circuit. 115

At this stage of the operation of the system, the sequence switch of the appropriated finder circuit F is in position 4, and the elevator rod of the associated line finder LF' is moving up with the set of brushes tripped that corresponds with the group in which the calling line is located. As the tripped brushes rise, they come into engagement consecutively with the sets of terminals corresponding with the different lines of the group. At the instant of engagement of the brush 42 with the corresponding line terminal 46 of each line, a circuit is closed that 125

extends from battery by way of the relay 52, sequence switch contacts 212 (2 to 4), conductor 50, brush 42, line terminal 46, conductor 53 and winding of cut-off relay 11 to ground. If a line is busy as a calling line, a branch path is in existence for the flow of current through the cut-off relay 11 by way of contacts 212 of another finder circuit sequence switch, and associated resistance 64 if the switch is in positions 4 $\frac{3}{4}$ to 12 $\frac{1}{2}$, or windings of associated relays 30 of the finder circuit and 155 of the connecting cord circuit if the switch is in positions 12 $\frac{3}{4}$ to 14. If the line is busy as a called line, a branch path is in existence by way of the windings of relays 119 and 175 associated with the connecting circuit calling plug (see Fig. 5). In either case, this branch path serves to shunt the relay 52 and prevent its operation as the finder brushes pass over the terminals of the corresponding line.

If the line over the terminals of which the brushes are passing is not busy, the relay 52 is operated, and in attracting its armatures closes a circuit that extends from battery through the lower winding of the relay 37, front contact and lower armature of the relay 52, sequence switch contact 213 (2 to 4), conductor 49, brush 41, line terminal 45, conductor 39 to one limb of the telephone line, thence by way of the path controlled in contacts of the substation switchhook, to the other limb of the line, conductor 38, terminal 44, brush 40, conductor 48, sequence switch contact 214 (2 to 4), upper armature and front contact of the relay 52, upper winding of the relay 37 to ground. The circuit traced above is not completed until the finder switch brushes engage the terminals of the calling line, as the calling line is the only line that has its telephone receiver off the hook, and at the same time is not connected with either by some other line finder or by a connecting circuit calling plug. The completion of this circuit energizes the relay 37 and causes that relay to interrupt in its back contact the circuit by way of the left-hand armature and front contact of the relay 30, sequence switch contacts 216, right-hand winding of relay 30, sequence switch contacts 217, and resistance 56 to battery, which had been holding relay 30 locked up from the moment that relay was first energized upon the receipt of the call.

Relay 30, in releasing its armatures, breaks its own locking circuit traced above, and also breaks the previously traced path including sequence switch contacts 208, right-hand front contacts of the relay 30 and sequence switch contacts 207, over which current has been flowing to energize the up-drive magnet 32 of the line finder. Therefore, the operation of the relay 37, upon the finding of the calling line, acts to effect the instant deenergization of the up-drive mag-

net 32 and thus to stop the brushes upon the terminals of the calling line.

In order that the brushes may always be stopped in registration with the line terminals, the locking circuit of the relay 30 has an alternative path to ground by way of sequence switch contact 215 (2 to 4), conductor 66, the C segment of the line finder commutator and the corresponding brush to ground. The C segment of the commutator is so formed and related to its brush that the connection between the two is interrupted only when the corresponding line brushes on the elevator rod are in engagement with corresponding set of line terminals. The unlocking of the relay 30, and the consequent stopping of the upward movement of the elevator rod, can therefore occur only when the line brushes are in proper relation to the terminals of the calling line.

When the relay 30 is deenergized, as a result of finding the calling line, it also completes a circuit that extends from battery through the motor magnet and contacts 202 (3 to 4) of the sequence switch 200, right-hand back contact and armature of the relay 30, sequence switch contacts 208 (18 to 14) and (2 to 7), conductor 79, segment M of the cord finder commutator and its corresponding brush to ground. The closure of this circuit moves the sequence switch out of position 4.

When the sequence switch reaches position 4 $\frac{3}{4}$, it closes a path for the flow of current through the cut-off relay 11 of the calling line by way of resistance coil 64, sequence switch contact 212 (4 $\frac{3}{4}$ to 12 $\frac{1}{2}$), conductor 50, brush 42, line terminal 46 and conductor 53. The flow of current in this path operates the cut-off relay 11 to disconnect the line relay 12 from the circuit, and that relay, in releasing its armature, disconnects ground from the common conductor 18. The times of operation of the various parts are so related that the line relay 12 is deenergized, in the manner described above, before the timing sequence switch 100 of the associated line group has completed its rotation and closed the circuit of conductor 18 in sequence switch contacts 103. The current which previously flowed through the cut-off relay 11 by way of the winding of relay 52 of the finder circuit had been insufficient to operate the cut-off relay by reason of the winding of relay 52 being of relatively high resistance.

The brushes of the line finder switch are now at rest in engagement with the terminals of the calling line, the group starting circuit represented by the conductors 57 and 58 and the associated common relay 22 has been released and is in readiness to respond to another calling line, and the sequence switch of another finder circuit has been moved into position 2, and thus brought into

operative relation with the starting conductor 29. The stages of the operation that are next to be described have to do with the selection by the appropriated finder circuit of an idle operator's position and the selection of an idle connecting cord on that position. When the finder sequence switch 200 reaches position 5, it closes a circuit that extends from battery by way of the winding 10 of relay 55, (Fig. 3), conductor 71, sequence switch contact 218 (5 to 8), conductor 67, commutator segment M of the line finder switch and corresponding brush to ground. The operation of the relay 55 applies ground 15 to the conductors 81 extending to all of the operators' positions to the connecting circuit terminals of which the cord finder switch of the finder circuit has access. At each of the positions where the operator is at her station and is in readiness to receive a call, the associated relay 91, (Fig. 4) is inert, and the operator's telephone sequence switch 300 is in its 1 position. Consequently, at each of such positions, a circuit is closed that extends 20 from battery through the winding of the associated relay 92, left-hand armature and back contact of relay 91, sequence switch contact 304 (1), conductor 81, armature and front contact of relay 55 to ground. The relay 92 of each awaiting position attracts its armature and closes a circuit that extends from battery through the front contact and armature of the relay 92 to the conductor 82, and thence to ground by way of the windings 25 of a number of relays 77 of which one is provided for each cord finder frame that has access to this particular operator's position. The particular nature of this connection of the different operators' circuits to a plurality 30 of finder frames will be explained later. For the present, the operation will be described merely in its relation to the particular finder frame that serves the finder circuit that has been assumed to have been appropriated by the calling line. For the present it will also further be assumed that the operator's position 0 is in readiness to receive a call.

The finder circuit sequence switch 200 35 does not stop in position 5, but continues its movement and comes to rest in position 6. Here it awaits the closing of a circuit the completion of which is dependent upon the condition of the other finder circuits of the 40 associated group. This circuit extends from battery through the left-hand winding of the relay 30, contact 219 (6) of the appropriated finder circuit sequence switch, contacts 219 (9 to 4) of the sequence switches 45 of the associated finder circuits preceding it in the series, conductor 76, outer armature and back contact of relay 54 and right-hand back contact and armature of relay 61 to ground. This circuit is open either in cam 50 55 60 65 219 of a preceding finder sequence switch

200 in the series, or in contacts of the relays 54 or 61 as long as any other sequence switch of the series is in same position between positions 4 and 9. That is, it is open from the time the line finder switch of any associated 70 finder circuit finds a calling line until the cord finder switch of that circuit has moved far enough to trip the brushes corresponding with the selector group. Not until this has occurred will the above-traced circuit of 75 the awaiting finder circuit be closed.

The closure of this circuit causes relay 30 to attract its armatures and complete a circuit that extends from battery through the motor magnet and sequence switch contact 80 202 (6) of the sequence switch 200, front contact and right-hand armature of relay 30, sequence switch contacts 208 (18 to 14) and (2 to 7), conductor 79, commutator segment M of the cord finder and corresponding brush to ground. The completion of this circuit moves the finder sequence switch out of position 6.

When the finder sequence switch reaches position $6\frac{1}{4}$, it closes a circuit that extends 90 from battery through the winding of relay 54, (Fig. 3), left-hand back contact and armature of relay 61, conductor 73, finder sequence switch contact 218 ($6\frac{1}{4}$ to 8), conductor 67, commutator segment M of the line 95 finder switch and corresponding brush to ground. Relay 54 attracts its armature and completes a branch of the circuit traced above which extends from conductor 73 by way of the armature and back contact of the relay 63, front contact and inner armature of relay 54, armature and front contact of relay 77 (which relay is energized, as previously described, as a result of the corresponding operator's position being in readiness 100 to receive a call), right-hand back contact and switch spring of relay 93 of the corresponding group, winding of associated 105 relay 94, winding of relay 93, left-hand switch spring and resting contact of relay 110 93, conductor 83, left-hand back contact and armature of relay 95 at the corresponding operator's position to battery. Upon the closure of the above-traced branch circuit, the group relays 93 and 94 are energized 115 in parallel with the relay 54. Relay 93, in operating, disconnects its own energizing winding and that of relay 94 from the previously-traced path to battery by way of the left-hand back contact and armature of the relay 95, and connects them in a path which extends from battery by way of the winding of the relay 95 and conductor 84. This causes the relay 95 also to be energized and to interrupt, in its left-hand armature and back contact, the path by way of conductor 83 over which the relays 93 and 94 were initially energized.

Relay 94, in operating, closes a circuit 120 from battery through the winding of the 125 130

trip magnet 22 of the group corresponding to the selected operator's position and to ground by way of the right-hand armature and front contact of the relay 94. This relay 5 also closes a circuit that extends from battery through the winding of the relay 63 and the left-hand armature and front contact of the relay 94 to ground. The relay 63, in operating, closes a branch that extends 10 from the conductors 73 (grounded at commutator segment M of the line finder switch) through the armature and front contact of relay 63, conductor 72, sequence switch contact 220 (7), and left-hand winding 15 of relay 30 to battery. Relay 30 attracts its armatures and closes a circuit that extends from battery through the motor magnet and sequence switch contact 202 (7), front contact and right-hand armature of relay 20 30, sequence switch contacts 208 (18 to 14) and (2 to 7), and thence to ground by way of the M commutator segment of the cord finder switch. The closure of this circuit moves sequence switch 200 out of position 25 7. Furthermore, relay 30, in operating, is locked up over a circuit that extends from battery through resistance 56, sequence switch contacts 217 (2 to 9), right-hand winding of relay 30, sequence switch contacts 216 (7 to 9) and (2 to 9), front contact and left-hand armature of relay 30 and armature and back contact of relay 37 to ground.

When the sequence switch reaches position 8, it closes a circuit that starts the upward movement of the brush-carrying rod of the cord finder switch, this circuit extending from battery through the up-drive magnet 34 of the cord finder, conductor 89, sequence switch contact 207 (8 to 9), right-hand front contact and armature of relay 30, sequence switch contact 218 (8 to 9), conductor 67, commutator segment M of the line finder and corresponding brush to ground.

At the outset of the upward movement of the cord finder brush rod, the tripping levers of the various sets of brushes are brought simultaneously into operative position 50 with respect to the corresponding tripping yokes, and that set of brushes is tripped and made operative whose trip magnet is at the time energized. In the present instance, it is assumed that this is the trip magnet 22 associated with the terminals of the group of connecting cord circuits extending to the 0 operator's position.

Immediately after the set of brushes is tripped, the common operator's selecting 60 circuit is restored so as to be available for the use of other cord finder switches. This is effected through the medium of a circuit that is completed by the grounding of the K segment of the cord finder commutator, 65 this segment being so located as to be en-

gaged by its brush immediately after the tripping levers of the sets of brushes pass the associated tripping yokes. The circuit referred to extends from battery through the winding of relay 61, conductor 74, sequence switch contact 221 (7 $\frac{3}{4}$ to 8), conductor 80, cord finder commutator segment K and its corresponding brush to ground. Relay 61, in operating, opens, in its left-hand back contact, the previously-traced circuit 70 by way of conductor 73 which, up to this time, has been holding energized the relay 95 at the 0 operator's position and the relays 93 and 94 corresponding to this position on the cord finder frame. The release of relay 94 deenergizes the corresponding trip magnet 22 and the common relay 63. The deenergization of the relay 93 reestablishes, subject to the release of relay 61, the control of other finder circuits over the brush 80 tripping mechanism of the associated cord finder frame. It also restores the corresponding operator's position to operative relation with the common selecting apparatus of other finder frames, in a manner which will 85 hereinafter be explained.

Relay 61, in operating, closes a locking circuit for itself by way of conductor 73, sequence switch contact 218 (6 $\frac{3}{4}$ to 8), conductor 67, commutator segment M of the line finder and corresponding brush to ground. It also completes a circuit that extends from battery through the motor magnet and contact 205 (8) of the sequence switch 200, conductor 75, right-hand front contact and armature of relay 61 to ground. The closure of this circuit moves sequence switch 200 out of position 8. In moving out of position 8, the sequence switch opens its contacts 218 (6 $\frac{3}{4}$ to 8) and 221 (7 $\frac{3}{4}$ to 8), 100 thus deenergizing relay 61 and again extending conductor 73 to the relay 54 and the conductors over which the operator's selection is effected. In closing its right-hand back contact upon release, relay 61 also restores the continuity of conductor 76 and makes it available for moving out of position 6 the sequence switch of some other finder circuit which may be waiting for access to the operator's selecting circuit.

When the sequence switch 200 is moved out of position 8, it moves into position 9 and there awaits the finding of an idle connecting cord circuit upon the operator's position that has been assigned. As the brush-carrying rod moves up, the brushes 111, 112, 113 and 114 of the set that has been tripped come into engagement successively with sets of terminals 115, 116, 117 and 118 corresponding with the different connecting 120 cord circuits located at that operator's position. When a cord circuit is not in use, its corresponding terminal 118 is connected directly to ground; and when the terminals of such a connecting circuit are encountered, 125 130

a circuit is completed that extends from battery through the lower winding of relay 37, sequence switch contacts 206 (8 to 9), conductor 99, brush 114, terminal 118, conductor 5 88, sequence switch contact 404 (1), right-hand back contact and armature of relay 119 to ground. Current flowing in this circuit causes the relay 37 to attract its armature and break the previously traced circuit by 10 way of sequence switch contacts 216 and 217 and the right-hand winding of relay 30, which, up to this time, has been holding relay 30 energized. It may here be noted that the locking circuit of relay 30 has a branch 15 to ground in parallel with the branch controlled in the back contact of relay 37, the branch referred to extending by way of sequence switch contact 215 (8 to 9), conductor 78, commutator segment C of the 20 cord finder switch and the corresponding brush to ground. This path serves the same function as has already been described in connection with the path by way of the C segment of the line finder commutator; that 25 is, it prevents the relay 37 from causing the deenergization of the relay 30 excepting when the brushes of the cord finder switch are centered upon their successively engaged sets of terminals.

30 When the relay 30 is released, as a result of the brushes engaging the terminals of a connecting circuit that is not in use, it opens, in its right-hand front contact, the previously traced circuit including the up-drive magnet 34, and thus causes the brushes of the cord finder switch to come to rest. The relay 30, in releasing, also closes a circuit that extends from battery through the motor magnet and contact 202 (9) of the sequence switch 200, back contact and right-hand armature of relay 30, sequence switch contact 218 (8 to 9), conductor 67, M segment of the line finder commutator and corresponding brush to ground. The closure 40 of this circuit moves the sequence switch 200 out of position 9.

45 It has previously been explained how, when the sequence switch of an appropriated finder circuit reaches position 6 $\frac{1}{2}$, it operates a particular trip magnet on the cord finder frame that corresponds with a waiting operator's position, and at the same time operates the relay 95 associated with the apparatus at that operator's position. When the 50 relay 95 at the operator's position attracts its armatures, it closes a circuit which extends from battery through the motor magnet and contact 303 (1) of the operator's sequence switch 300, conductor 121, right-hand front contact and armature of relay 95, conductor 123, right-hand front contact and armature of relay 125 to ground. The closure 55 of this circuit causes the operator's sequence switch 300 to move out of position 60 1.

It may be well at this point to explain that the operator's sequence switch, as indicated by the numerals applied to sequence switch cam 301, is adapted to rest in three positions,—namely, positions 1, 4 and 17. 70 The energizing circuit of the relay 125 is controlled in local contacts 127 of the operator's telephone jack 126. When the operator is at her position, these contacts are closed and the relay 125 is energized. At 75 such a time, a circuit is closed that extends from battery through the motor magnet and contact 303 (4) of the operator's sequence switch and the left-hand front contact and armature of relay 125 to ground. Therefore, while the operator is at her station it is impossible for the operator's sequence switch to rest in position 4. When the operator leaves her station the deenergization of relay 125, as a result of the withdrawal 80 of the operator's telephone plug from the jack 126, closes a circuit that extends from battery through the motor magnet and contact 303 (1 and 17) of the operator's sequence switch, left-hand back contact and 85 armature of relay 125 to ground. Therefore, when the operator is not at her station, the sequence switch 300 is automatically moved out of positions 1 and 17, and can rest only in position 4. 90

When the operator's sequence switch moves out of position 1 as a result of the selection of the operator's position and the actuation of relay 95, a circuit is closed that extends from battery through the winding 100 of relay 145, upper back contact and armature of relay 153, sequence switch contacts 304 (2 to 16), outer back contact and armature of relay 142, sequence switch contact 305 (1 to 16) sequence switch contact and right-hand front contact and armature of relay 125 to ground. As a result of the 105 flow of current in this circuit, the relay 145 attracts its armature and closes a circuit that extends from the device 143 for producing a characteristic tone, through a condenser 144, right-hand front contact and armature of relay 145 and winding 146 of the induction coil of the operator's telephone set 147 to ground. The result, therefore, is that an 110 instant after the operator's sequence switch is moved out of position 1, as a result of the selection of that particular operator's position by the seeking finder circuit, a call tone is applied to the operator's telephone receiver which warns the operator that her 115 position has been selected and that a call is coming.

The manner in which the selection of an 120 idle cord circuit is accomplished by the seeking cord finder switch, and the manner in which such selection moves the finder sequence switch 200 out of position 9, whence it moves into position 14, have already been 125 described. As long as the finder sequence 130

switch 200 is in position 9, the conductor extending from the third or sleeve brush 42 of the line finder is connected with battery by way of sequence switch cam 212 and 5 resistance coil 64, to hold the cut-off relay 11 of the calling line energized; and the conductor 98 extending from the third or sleeve brush 113 of the cord finder switch is open at sequence switch cam 217. When the 10 finder sequence switch reaches position 9 $\frac{3}{4}$, it closes a circuit, which will be traced hereinafter, for the energization of relays 151, 154 and 157 of the connecting cord circuit. This last-mentioned circuit is maintained until 15 the finder sequence switch 200 moves out of position 11, when it is interrupted in contacts of cam 217. An instant later, in position 12 of the sequence switch, the cam 217 acts to extend the sleeve conductor 98 through 20 the right-hand winding of the relay 30 to contacts of the cam 212, which are closed a moment later in position 12 $\frac{3}{4}$ of the sequence switch. In moving from position 12 $\frac{3}{4}$ to position 12 $\frac{1}{4}$, the sequence switch 200, by the 25 action of cam 212, substitutes the path last referred to by way of the right-hand winding of the relay 30 for the path by way of the resistance coil 64, over which, up to this moment, the cut-off relay 11 of the calling 30 line had been maintained energized. From the moment the finder sequence switch 200 reaches position 12 $\frac{3}{4}$, therefore, the cut-off relay 11 and the relay 30 of the finder circuit are included serially in a circuit that 35 maintains their energization, and as long as the continuity of the circuit is maintained, the finder circuit is held in its talking condition.

As was stated in the foregoing, when the 40 finder sequence switch 200 reaches position 9 $\frac{3}{4}$, after the brushes of the cord finder switch have come to rest upon the terminals of the idle connecting cord circuit, a circuit is completed for the energization of 45 relays 151, 154 and 157 of the connecting cord circuit. This circuit may be traced from battery through the windings of relays 151, 154 and 157 in parallel (the branch through the winding of relay 157 also passing 50 through contacts 509 (1) of the calling cord sequence switch 500) to sequence switch contacts 505 (1), and thence by way of listening-key sequence switch contacts 405 (1), left-hand back contact and armature of relay 152, conductor 87, contact 117 and brush 113 of the cord finder switch, conductor 98, sequence switch contacts 217 (9 $\frac{3}{4}$ to 14) and (9 $\frac{3}{4}$ to 11), and resistance coil 36 to ground. Therefore, an instant after the idle connecting 60 cord circuit has been appropriated and the finder sequence switch 200 moved out of position 9, the three relays 151, 154 and 157 of the connecting cord circuit are operated.

65 Relay 154, in operating, closes, in its arma-

ture and front contact, a locking circuit for all three of the relays, which circuit extends by way of calling cord sequence switch contacts 506 (1), and listening key sequence switch contacts 406 (1 to 6) to ground. The 70 three relays are thus held locked up while the listening-key sequence switch 400 is moving from its normal position 1 to its listening-in position 7. This movement of the listening-key sequence switch is effected by 75 a circuit that extends from battery through the motor magnet and contacts 403 (1) of the sequence switch 400, sequence switch contacts 507 (17 to 8) and (1) and right-hand front contact and armature of relay 154 to 80 ground. In leaving position 1, the listening-key sequence switch 400 breaks, in contacts 405 (1), the connection of the sleeve conductor 87 with battery by way of the windings of relays 151, 154 and 157. But relay 85 151, in operating, has in the meanwhile completed a circuit that extends from battery through the winding of relay 152 and outer front contact and armature of relay 151 to ground. As a result, relay 152 is energized 90 and in its left-hand armature and front contact has disconnected the conductor 87 from the branch extending by way of sequence switch contacts 405 (1), and has connected it instead with battery by way of the left- 95 hand switch spring and resting contact of relay 156 and the winding of relay 155. The relay 155 thereupon operates to close the circuit of the talking conductor 86 which is normally maintained open for a reason 100 which will hereinafter be explained.

After relay 152 is initially energized by the operation of the relay 151, it is maintained operated by a path to ground that 105 is closed by way of cam 407, as soon as the listening-key sequence switch reaches position 2 and thereafter until it moves out of its listening-in position 7.

When the relays 151 and 157 operate at the moment the idle connecting cord circuit is seized, they effect certain changes in the condition of the operator's telephone circuit, which will now be described. When relay 151 operates, it closes a circuit that extends from battery through the winding of relay 110 153 of the operator's circuit (see Fig. 4), conductor 129, calling cord sequence switch contact 502 (1), and inner front contact and armature of relay 151 to ground. Relay 153 operates, and in its upper armature and 115 back contact opens the circuit over which, up to this moment, the relay 145 had been maintained energized. Relay 145 thereupon releases its armature, and opens the circuit, previously traced, over which the calling 120 tone from the device 143 had theretofore been supplied to the operator's telephone apparatus. The ceasing of this tone in her telephone notifies the operator that the incoming call has been extended to one of her 130

connecting cord circuits. Which of the connecting cord circuits at her position has been appropriated is indicated to the operator by the flashing of the lamp 161 associated with that cord. The circuit by means of which this is effected extends from battery through the resistance 163, lamp 161, calling cord sequence switch contacts 514 (1 to 2), listening-key sequence switch contacts 412 (1 $\frac{3}{4}$ to 18 $\frac{1}{4}$) and call signal interrupter 162 to ground. The lamp is thus caused to flash as soon as the listening-key sequence switch moves into position 1 $\frac{3}{4}$.

Relay 157, in operating, at the instant the cord circuit is seized, connects the operator's telephone set with the telephone of the calling subscriber. This circuit may be traced from the operator's telephone apparatus by way of conductors 135 and 136, conductors 167 and 168, calling cord sequence switch contacts 512 (1) and 513 (1) and corresponding inner contacts and armatures of relay 157, calling cord sequence switch contacts 510 (1) and 511 (1), conductors 169 and 170, back contacts and armatures of relay 158, conductors 85 and 86, terminals 115 and 116 and corresponding brushes 111 and 112 of the cord finder switch, cord finder conductors 96 and 97, finder sequence switch contacts 214 (9 $\frac{3}{4}$ to 14) and 213 (9 $\frac{1}{4}$ to 14), line finder conductors 48 and 49, line finder brushes 40 and 41 and corresponding line terminals 44 and 45, and line conductors 38 and 39 to the telephone apparatus at the calling station.

The circuit between the operator's telephone and the telephone at the calling subscriber's station is completed the instant the connecting cord is seized. At the same instant, as previously described, the relay 154 operates to close the circuit for moving the listening-key sequence switch 400 out of its 1 position. Sequence switch 400 continues to move until it reaches position 7, where 45 it comes to rest. Just before the sequence switch reaches position 7, it opens the circuit, by way of sequence switch contact 406 (1 to 6), and left-hand armature and front contact of relay 154, over which the relay 157 and 50 its associated relays 151 and 154, had been held energized; and at the same moment, it completes an alternative path for the connection of the operator's telephone with the calling subscriber's telephone. This alternative path extends from the operator's telephone apparatus 147 by way of conductors 135 and 136, resting contacts of the ring-back key 160 and the coin-return key 159, listening-key sequence switch contacts 408 55 (6 to 8) and 409 (6 to 8), and resting contacts and armatures of relay 158 to the conductors 85 and 86, whence the circuit is as previously traced to the calling subscriber's line and telephone apparatus. The connection 60 between conductor 136 and conductor 65

86 also includes contacts of the relay 155 which are closed at this time, the relay 155 being energized over a path previously traced.

When the listening-key sequence switch reaches position 7, therefore, the bypass to the operator's telephone by way of the contacts of relay 157 is opened, and the main path by way of the sequence switch contacts 408 (6 to 8) and 409 (6 to 8) is closed. The object of providing the bypass closed instantly by the relay 157 upon the seizure of the connecting cord circuit, is to save the time required for the sequence switch 400 to close the direct path by way of its cams 80 408 and 409, and thus place the operator in communication with the calling subscriber a little sooner than would be the case if the establishment of the circuit waited upon the movement of the sequence switch. In the 85 operation of a system such as that herein disclosed where the traffic is heavy, the resultant saving of time of the operator and the calling subscriber, although slight, is of practical importance.

At the stage of the operation that has now been reached, the operator's telephone sequence switch 300 is resting in position 17, and the listening-key sequence switch 400 is resting in position 7. In position 7 of the listening-key sequence switch, each of the talking conductors 85 and 86 of the circuit is severed, and is connected in a loop which may be traced through the operator's circuit by way of listening-key sequence switch contacts 408 (6 to 8) and 409 (6 to 8), conductors 135 and 136, including the resting contacts of the coin-return key 159 and the ring-back key 160, conductors 165 and 166, and listening-key sequence switch contacts 410 (6 to 8) and 411 (6 to 8). From this point, the circuit of the talking conductors extends to opposite poles of the battery by way of two windings of the cord circuit repeating coil 169, the other two windings of the repeating coil being included in conductors that extend from the poles of the battery to the tip and ring contacts respectively, of the calling plug 170, when certain apparatus hereinafter to be described is operated.

The extension of the talking conductor 86 to the free pole of the battery by way of its corresponding repeating coil windings, includes the winding of the answering supervisory relay 171, so that in position 7 of the listening-key sequence switch, the supervisory relay 171 is included in the circuit that extends to the calling subscriber's line and station. This relay controls the illumination of the answering supervisory lamp 172 by controlling a shunt about the lamp including the resistance 173. When the listening-key sequence switch moves out of position 1, upon the seizure of the cord circuit, 130

it closes a circuit that extends from battery through resistance 174, answering supervisory lamp 172 and sequence switch contacts 407 (1 $\frac{1}{2}$ to 18 $\frac{1}{2}$) to ground. The current flowing in this circuit tends to light the lamp 172; but the illumination of the lamp is prevented by the fact that the answering supervisory relay 171 is energized over the circuit which at this time is closed at the 5 calling subscriber's station. The answering supervisory lamp 172 is thus shunted and prevented from lighting.

When the operator is informed, by the cessation of a call tone in her telephone receiver and by the lighting of the call lamp 161 that she is connected with the calling line, she speaks to the calling subscriber and ascertains the number of the line with which he desires connection. She then lifts the 10 calling plug 170 of the connecting cord identified by the flashing call lamp 161, and tests the line with which connection is desired by touching the tip of the plug to the sleeve of the corresponding spring-jack 14. Assume that the called line is similar in its 15 equipment and circuit connections to the lines which are illustrated in Fig. 1. In this case, the tip, ring and sleeve contact portions of the spring-jack 14 are connected with conductors 38, 39 and 53, respectively, which extend to the stationary terminals 44, 45 and 46 of a finder switch. If the called line is 20 busy, by reason of the brushes of a finder switch being in engagement with these terminals, battery is applied to the finder switch terminal 46 of that line and by way of conductor 53, and its multiple connections, to the 25 sleeve of the corresponding spring-jack 14. When the sequence switch of the finder circuit is standing in position 4 $\frac{1}{2}$ to 12 $\frac{1}{2}$, battery is applied by way of the resistance coil 64 and sequence switch cam 212. When the sequence switch 200 is standing in positions 12 $\frac{1}{2}$ to 14, battery is applied by way of the 30 winding of relay 155 of the connecting cord circuit. In case the line with which connection is desired is busy as a called line, battery is applied to the sleeve of the tested spring-jack by way of the windings of relays 119 and 175, the sleeve of the calling plug 170 of the 35 cord circuit that is already connected with the line, and the multiple connection between the sleeve of the spring-jack that is connected with and the sleeve of the spring-jack that is being tested.

When the tip of the calling plug 170 is touched to the sleeve of the spring-jack of such a line, current flows by way of the tip of the plug, right-hand armature and back contact of relay 175, conductor 133 and winding of the operator's test relay 184 to ground. This relay, in attracting its armature, closes a circuit that extends from battery through a retardation coil 185, front contact and 40 armature of relay 184 and winding 146 of

the induction coil of the operator's telephone set 147 to ground. The closure of this circuit causes a click in the operator's telephone receiver which notifies her that the line is busy. The operator may then tell the calling subscriber that the called line is busy, and release the connection by pressing her master listening-key 186. The manner in which this effects the release will be described hereinafter.

If the called line is not in use, there will be no battery connection with the sleeve of the tested jack, and no click will be produced in the operator's telephone receiver. Consequently, she will insert the plug 170 45 into the spring-jack 14. The insertion of the plug in the jack closes a circuit that extends from battery through the windings of the relays 119 and 175 in series, and thence by way of the registering sleeve contacts of the plug 170 and spring-jack 14 to ground 50 by way of the winding of the cut-off relay 11. The cut-off relay 11 disconnects the line relay 12 from the circuit. The relay 175, in its right-hand armature and back contact, 55 disconnects the tip of the plug from the conductor 133 extending to the operator's busy test relay 164, and connects it instead with the tip conductor of the talking circuit. Relay 175 also closes a circuit that extends 60 from battery through the motor magnet and contacts 503 (1) of the calling cord sequence switch, contacts 413 (7) of the listening-key sequence switch, left-hand front contact and armature of relay 175 and normally closed contacts of the charge key 176 to ground. The closure of this circuit energizes the motor magnet and moves the calling cord sequence switch out of position 1. When the calling cord sequence switch 65 reaches position 2, it comes to rest and completes a circuit that extends from battery through the motor magnet and contact 403 (7) of the listening-key sequence switch, contact 515 (2) of the calling cord sequence switch, and right-hand back contact and armature of relay 154 to ground. When the listening-key sequence switch 400 moves out of position 7 as a result of the closure of this circuit, it completes a circuit that extends from battery through the motor magnet and contact 504 (2) of the calling cord sequence switch, contact 413 (8 to 15) of the listening-key sequence switch, left-hand front contact and armature of relay 175, and resting contact of the charge key 176 to ground. The closure of this circuit moves the calling cord sequence switch out of position 2. As the listening-key sequence switch 400 120 moves out of position 8, it operates its cams 408, 409, 410 and 411 to disconnect from the connecting cord circuit the loop that extends to the operator's telephone circuit by way of the conductors 135, 136 and 165, 166, 130

and connects the talking conductors 85 and 86 of the connecting cord circuit directly through to the left-hand windings of the repeating coil 169. Furthermore, in moving out of position 7 it interrupts the branch of the energizing circuit of the cord circuit holding relay 152 that had been completed to ground by way of listening-key sequence switch contacts 407 (2 to 7), and leaves the continued energization of the holding relay dependent upon a path to ground that extends by way of the right-hand front contact and armature of relay 152 and contact 508 (1 $\frac{1}{2}$ to 17 $\frac{1}{2}$) of the calling cord sequence switch.

After the calling cord sequence switch 500 is moved out of position 2 by the movement of the listening-key sequence switch out of position 7, as described above, it moves through its various stages until it reaches position 12, at which point a circuit is closed that extends from battery through the winding of relay 180, left-hand armature and back contact of relay 178, armature and back contact of relay 177, sequence switch contacts 507 (12 to 13) and (10 to 15), sequence switch contacts 516 (3 to 13) to ground. The closure of this circuit energizes relay 180 and causes it to open in its right-hand armature and back contact a circuit by way of contact 504 (4 to 13) of the calling cord sequence switch, which theretofore had maintained the energization of the motor magnet of that switch. As the cam 501 of the calling cord sequence switch is cut so as to keep the energizing circuit of the motor magnet closed in position 12 of the sequence switch, the switch continues to move until it reaches position 13, where it comes to rest.

In position 13 of the calling cord sequence switch, ringing current is applied to the connecting cord circuit to ring the bell at the called subscriber's station. This is effected through the medium of a circuit which has two branches alternately closed in the rotation of the commutator 182, one of the branches including the battery and the other including a source of ringing current 181. From the commutator 182, the circuit extends by way of sequence switch contact 517 (13), winding of relay 177, left-hand armature and front contact of relay 180, sequence switch contact 519 (13), ring contact of the calling plug 170, ring spring of the spring-jack 14, and thence over the corresponding side of the line to the called subscriber's station, where it is connected to ground by way of the substation condenser and bell. At the same time, the other side of the called subscriber's line is connected directly to ground by way of sequence switch contacts 518 (13).

The closure of this circuit causes the bell at the substation to ring intermittently, and

also, by the diversion of a small part of the alternating current by way of the condenser 183 and the upper right-hand winding of the repeating coil 169, indicates to the calling subscriber the application of ringing current to the line of the called subscriber. When the called subscriber, responding to the ringing of the bell, takes his telephone receiver from its hook, the resultant closure of a relatively low resistance path across the limbs of the line causes an increase in the current flow over the circuit just traced and brings about the energization of the relay 177. This relay is preferably so constructed and adjusted, in any well-known way, as to make it insensitive to the alternating current flow that passes through it during the ringing of the bell, but responsive to the current flow that takes place when the telephone receiver is taken from its hook.

When the relay 177 operates, it opens the short circuit that normally exists about the winding of the relay 178, which relay is included in the path previously traced through the relay 180 and cams 507 and 516 of the calling cord sequence switch. The removal of the short circuit causes relay 178 to attract its armatures. The opening of the left-hand armature and back contact of the relay 178 prevents the reestablishment of the short circuit about the winding of relay 178 when the armature of relay 177 falls back after a momentary attraction. The engagement of the right-hand armature of relay 178 with its front contact closes a path from battery including a resistance coil 179, which is in parallel with the path from battery including the relay 180. The resistances of the coil 179 and the winding of the relay 180 are so proportioned that the relay 180 is shunted and releases its armatures. The left-hand armature of relay 180, in falling back, opens the previously traced path over which ringing current was applied to the connecting cord circuit. The right-hand armature of relay 180, in releasing and closing its back contact, closes a circuit that extends from battery through the motor magnet and contact 504 (4 to 13) of the calling cord sequence switch. This causes the sequence switch to move out of position 13.

The calling cord sequence switch 500 is indicated as being adapted, after leaving position 2, to come to rest in positions 4, 5, 7, 8, 10 and 11, as well as in position 13 as described above. These positions of the sequence switch may be employed for the purpose of effecting the application to the connecting circuit of ringing currents of different characteristics for the purpose of selectively ringing the bells of party lines. The movement of the sequence switch in and through these positions may be under

the control of a branch of the energizing circuit of the relay 180 which extends to a cam 520 of the calling cord sequence switch, and may be further controlled by a branch 5 of the energizing circuit of the motor magnet of sequence switch 500 which is adapted to be closed in positions 4, 7 and 10 of the sequence switch cam 504. The application of partly line ringing current to the connecting cord circuit may be effected through the medium of contacts of the calling cord sequence switch cams 518 and 519, closed in positions 5, 8 and 11. The particular method in which this is accomplished is 10 disclosed and claimed in my Patent 1,251,604 issued January 1, 1918, but inasmuch as this is a feature with which the present invention is not concerned, it is not herein shown.

When the calling cord sequence switch 20 leaves position 13, it moves to position 16. In this position, a circuit is completed that extends from battery through the lower right-hand winding of the repeating coil 169, calling supervisory relay 187, sequence 25 switch contact 519 (16 to 17), engaging ring contact surfaces of the calling plug 170 and called line spring-jack 14, thence to the called subscriber's station, over one limb of the line, through the substation apparatus 30 and back over the other limb of the line to the engaging tip contact surfaces of the spring-jack 14 and calling plug 170, right-hand armature and front contact of relay 175, sequence switch contact 518 (14 to 17) 35 and upper right-hand winding of the repeating coil 169 to ground. The current flowing in this circuit energizes the calling supervisory relay 187 and causes it to close a circuit that extends from battery through 40 the motor magnet and contact 503 (16) of the calling cord sequence switch, and armature and front contact of relay 187 to ground. This moves the sequence switch out of position 16, whereupon it moves to 45 position 17, which is the talking position.

Up until this moment, the lamp 161, which, as described, was caused to flash when the call first came in, has been burning steadily as a ringing lamp, the circuit for its illumination being to ground by way of contact 516 (3 to 16) of the calling cord sequence switch. When the sequence switch moves out of position 16, this circuit is interrupted and lamp 161 is extinguished. At the same 50 time, a circuit is closed from battery through resistance coil 188, and thence by way of two branches, one of which extends through the calling supervisory lamp 189, left-hand front contact and armature of relay 119 and sequence switch contact 521 (17) to ground 55 and the other one of which extends by way of resistance coil 190, sequence switch contacts 514 (17), and armature and front contact of relay 187 to ground. The resistance 60 in the latter branch is low, as a result of

which the calling supervisory lamp 189 is shunted out as long as the calling supervisory relay 187 is energized.

When this stage has been reached in the operation of the system, the talking circuit 70 is complete between the calling subscriber and the called subscriber. The finder circuit sequence switch 200 is in position 14, the connecting cord sequence switch 500 is in position 17 and the listening-key sequence 75 switch is in position 15, the listening-out position. In this condition of the circuit, the calling subscriber has control over the answering supervisory lamp 172 through the medium of the answering supervisory relay 171, and the called subscriber has control over the calling supervisory lamp 189 through the medium of the calling supervisory relay 187. As long as both subscribers 80 have their telephone receivers off the switchhooks, these lamps are dark. When either one of the subscribers hangs up, the corresponding lamp is lighted. When both lamps light at the same time, the operator knows that the conversation is at an end and 85 takes down the connection.

The operator disconnects by removing the calling plug 170 from the spring-jack of the called subscriber's line. This act permits relays 119 and 175 of the connecting cord 95 circuit and the cut-off relay 11 of the called subscriber's line to fall back. The cut-off relay 11, in falling back, reconnects the line relay 12 with the called subscriber's line. Relay 119, in releasing its right-hand armature to engage its back contact, reconnects ground with the conductor over which the cord finder tests the cord circuit. But the test conductor 88 is not made continuous to ground, and the cord circuit is therefore not 100 made selectable until the listening-key sequence switch cam 404 is closed upon the return of that sequence switch to its 1 position. The other armature of the relay 119, in disengaging its front contact, extinguishes the calling supervisory lamp 189. 110

Relay 175, in permitting its left-hand armature to engage its back contact, completes a circuit that extends from battery through the winding of relay 157, sequence switch 115 contacts 512 (2 to 17), left-hand back contact and armature of relay 175, and resting contacts of the charge key 176 to ground. Relay 157, in operating, closes a locking circuit for itself that extends by way of sequence switch contacts 512 (2 to 17), inner front contact and armature of relay 157, and sequence switch contact 510 (2 to 17) to ground. Relay 157 also closes a circuit that extends from battery through the motor 125 magnet and contact 503 (2 to 17) of the calling cord sequence switch, outer front contact and armature relay 157, and sequence switch contact 511 (2 to 18), to ground. The closure of this circuit moves 130

the calling cord sequence switch 500 out of position 17, whereupon it continues to rotate until it reaches and comes to rest in position 1, its normal position.

5 An instant after leaving position 17, the sequence switch 500 opens, in its contacts 508 (14 to 17), the path over which, up to this time, the holding relay 152 has been maintained energized. The relay 152 releases its armatures and brings about the return to normal of the finder circuit and its associated apparatus in a manner presently to be described. When the calling cord sequence switch 500 reaches position 1, it completes a circuit that extends from battery through the motor magnet and contacts 403 (15) of the listening-key sequence switch, contacts 515 (1) of the calling cord sequence switch, and right-hand back contact and armature of relay 154 to ground. This moves the listening-key sequence switch 400 out of position 15 and permits it to return to normal under the control of its cam 401.

When the holding relay 152 of the connecting cord circuit becomes inert, it breaks, in its left-hand armature and front contact, the circuit by way of conductor 87 of the connecting cord circuit, conductors 98 and 50 of the finder circuit and conductor 53 of the calling line, including windings of relays 155 of the cord circuit, 30 of the finder circuit and 11 of the calling line. Consequently, these three relays instantly release their armatures. The cut-off relay 11 of the calling line, in releasing its armatures, reconnects the line relay 12 with the line conductors 38 and 39. The circuit of the line is open at the subscriber's station, as a result of the calling subscriber having 40 replaced his telephone receiver on its hook; but the line finder and cord finder switches and the finder sequence switch 200 have not yet acted to disconnect the talking conductors of the line from the repeating coil 169 in the connecting cord circuit. The talking battery associated with the repeating coil may, under certain circumstances, be of lower potential than the line battery. When this is the case, the circuit that the line relay with its higher potential battery gets by way of the repeating coil during the interval before the switches act to break the connection would cause a momentary reenergization of the relay and the starting of another 45 finder switch. It is to prevent this that the relay 155 in the connecting cord circuit is provided. This last mentioned relay, being included in the same circuit, operates at the instant the cut-off relay operates, and opens 50 the conductor 86 of the talking circuit, thus opening the energizing path that the line relay 12 otherwise would have through the repeating coil 169.

When relay 30 of the finder circuit releases, it closes a circuit that extends from

battery through the motor magnet and contact 202 (8 to 14) of the finder sequence switch, left-hand back contact and armature of relay 30, and armature and back contact of relay 37 to ground. This moves the finder sequence switch out of position 14. When the finder sequence switch reaches position 15, it is moved through that position by means of a circuit that is completed from battery through its motor magnet and contact 202 (15), right-hand back contact and armature of relay 30, sequence switch contacts 218 (15), conductor 67, M segment of the line finder commutator and its corresponding brush to ground. The line finder sequence switch comes to rest in position 16. In this position a circuit is completed that extends from battery through the down-drive magnet 62 of the line finder switch, sequence switch contacts 208 (16), conductor 79, M segment of the cord finder commutator and corresponding brush to ground. The completion of this circuit energizes the down-drive magnet and causes the brushes of the line finder switch to return to normal. 90

When the brushes reach their normal position, a circuit is closed that extends from battery through the motor magnet and contact 205 (16) of the finder sequence switch, conductor 69, segment Y of the line finder commutator and its corresponding brush to ground. This moves the finder sequence switch out of position 16. In position 17, the next resting position of the finder sequence switch, a circuit is closed that extends from battery through the down-drive magnet 35 of the cord selector switch, conductor 90, sequence switch contact 218 (17), conductor 67, line finder commutator segment M and its corresponding brush to ground. 100 The closure of this circuit energizes the down-drive magnet 35 and causes the cord selector brushes to return to their normal position. At the end of the downward movement of the brushes, a circuit is closed that extends from battery through the motor magnet and contact 205 (17) of the finder sequence switch, conductor 31, Y segment of the cord selector commutator and corresponding brush to ground. The completion 110 of this circuit moves the finder sequence switch 200 out of position 17, after which it returns to position 1 under the control of its cam 201.

During the return movement of the line finder and cord selector brushes, the conductors terminating upon these brushes are open in their respective sequence switch cams, all of which cams, it will be noted, interrupt the circuits of their conductors as 125 soon as the finder sequence switch moves out of its talking position 14.

Thus, as described above, the withdrawal of the calling plug 170 from the spring-jack of the called line is effective in restoring to 130

their normal condition all of the switches involved in the extension of the connection from the calling to the called subscriber's line.

- 5 In order to describe further operations for which the system of this invention provides, it will now be assumed that after the connection between the calling subscriber and the called subscriber has been established, the operator has occasion to listen in on the connection. It may be that she will do this of her own initiative, or that she will be called in on a connection by the lighting of one or the other of the supervisory lamps 172 and 189. In listening in on a connection, the operator depresses the listening-in key 191 associated with the particular cord circuit over which the connection is established. At this time, the listening-key sequence switch 400 is standing in its listening-out position 15, having been moved to that position when the calling plug 170 is inserted in the spring-jack of the called subscriber's line. When the operator 20 presses the listening-in key 191, a circuit is closed that extends from battery through the motor magnet and switch contact 402 (15) of the listening-key sequence switch, conductor 130, contacts 304 (16 $\frac{1}{4}$ to 1) of the operator's sequence switch, conductor 122, right-hand back contact and armature of relay 95, conductor 123, and right-hand front contact and armature of relay 125 to ground. The closure of this circuit causes 25 the listening-key sequence switch to move out of position 15. When the sequence switch moves out of position 15, as a result of taking down the connection, it moves to position 1 and there comes to rest. But, in 30 the present case, it moves through position 1, as a result of a circuit that is completed from battery through the motor magnet and contact 402 (1) of the listening-key sequence switch and contacts 511 (2 to 18) of the 35 calling cord sequence switch to ground, the calling cord sequence switch at this time standing in its talking position 17. Consequently, the listening-key sequence switch moves on and comes to rest in its listening- 40 in position 7, in which position the operator's telephone loop, including the conductors 135, 136 and 165, 166, is again included, through the operation of the listening-key sequence switch cams 408, 409, 410 and 411, in the talking circuit between the calling subscriber and called subscriber. The operator is thus placed in condition to 45 supervise the connection and converse with either or both subscribers. She may, then, if she desires, again disconnect her telephone from the circuit by pressing her listening-out key 186. This key is common to all of the cord circuits of her position, and when it is pressed, it operates to close a circuit 50 that extends from battery through the motor

magnet and contact 403 (7) of whichever of the listening-key sequence switches is standing in position 7, and to ground by way of the closed contacts of the listening-out key. The completion of this circuit energizes the motor magnet and causes the associated listening-key sequence switch to move from position 7 to its listening-out position 15. 70

In an earlier portion of the description, it has been explained how the selectable condition of any operator's position is effectively indicated to the corresponding group selecting apparatus on the cord selector frame by the energization of the corresponding group relay 77; and how this is effected through the medium of the relay 92 at each operator's position, which relay may be energized under the control of the common relay 55 at the cord selector frame when any of the associated finder circuit sequence switches reaches position 5. It will now be explained how the energization of each group selecting relay 77, upon the energization of the common relay 55, is made subject 80 to the control of the corresponding operator's position apparatus with respect to the idle or busy condition of that apparatus and the consequent availability of that position 85 for receiving incoming calls. 95

It will be noted that in the energizing circuit of the relay 92 at the operator's position there are two control points, one of these points being the contact 304 (1) of the operator's sequence switch, and the other being the back contact and left-hand armature of the relay 91. It follows that the operator's sequence switch must be in position 1 and the relay 91 must be inert, in order that the relay 92 may be operated to cause 100 the corresponding group relay 77 to close the selecting path to the associated relays 93 and 94. 105

The sequence switch contact 304 (1) is opened as soon as the operator's position is 110 selected. This is accomplished, as has hereinbefore been explained, by the energization of the motor magnet of the operator's sequence switch 300 by way of contacts 303 (1), and right-hand front contact and armature of the relay 95 when that relay is operated as a result of the selection of the operator's position. The relay 91 is operated to open its contacts and render the position unselectable when a circuit is completed 115 through either one of its energizing windings. 120

In the listening-in operation, the depression of the listening-in key 191, in addition to the path through the motor magnet of the 125 listening-key sequence switch already described, completes a circuit that extends from battery through the left-hand winding of the relay 91. Conductor 138, listening-key sequence switch contacts 414 (9 to 16), left- 130

hand contact and switch spring of the listening-in key 191, conductor 130, operator's sequence contacts 304' (16 $\frac{1}{2}$ to 1), conductor 122, right-hand back contact and armature of relay 95, conductor 123, and to ground by way of the right-hand front contact and armature of relay 125. As a result, when any listening-in key 191 is pressed, the relay 91 opens the path through its left-hand armature and back contact and renders the operator's position instantly unselectable. In the listening-in operation, current is also caused to flow through the winding of relay 142, which is connected in parallel with the left-hand winding of the relay 91 in this same circuit. Relay 142 closes a circuit that extends from battery through the motor magnet and contact 303 (1) of the operator's sequence switch, assuming that the sequence switch is in position 1 when the listening-in key is pressed, outer front contact and armature of relay 142, contact 305 (1 to 16) of the operator's sequence switch, and right-hand front contact and armature of relay 125 to ground. This moves the operator's sequence switch out of position 1, and in doing so, breaks the operator's position test-control circuit in sequence switch contacts 304 (1) an instant after that circuit has been broken, as described, in contacts of the relay 91. The relay 142 at the same time closes a locking circuit for itself and for the relay 691 that extends by way of the inner front contact and armature of relay 142, sequence switch contact 305 (1 to 16), and the right-hand contact and armature of relay 125 to ground.

As previously described, the movement of the operator's sequence switch out of position 1 operates, through the medium of the relay 145, to apply a call tone to the operator's telephone receiver. This tone is of use when the movement of the sequence switch out of position 1 is occasioned by the selection of the operator's position by an incoming call. But where the movement of the sequence switch is the result of the operator's listening in on a connection, as in the present case, it is desirable that the call tone shall not be produced; and, consequently, the relay 142, when it operates to move the operator's sequence switch out of position 1, at the same time interrupts, in its outer armature and back contact, the circuit over which the call tone relay 145 would otherwise be energized in positions 2 to 16 of the sequence switch.

The locking circuit for the relays 91 and 142 is maintained by way of cam 305 of the operator's sequence switch as long as the switch is moving between positions 1 and 16, and is broken when the switch comes to rest in position 17.

It may be that when the operator depresses her listening-in key 191, the operator's sequence switch 300 is resting in position 17. In this case, relays 91 and 142 are both oper-

ated by way of the path previously traced, but the outer armature and contacts of the relay 142 and the left-hand armature and contact of relay 91 now perform no function, as the paths which these parts are adapted to control are opened in contacts of the sequence switch 300. The right-hand armature and contact of relay 91, however, interrupt a path over which the relay 192 is adapted to be energized, the purpose of which relay will hereinafter be explained. The inner armature and front contact of relay 142, also, in this case, close a locking circuit for the relays 91 and 142 which extends to ground by way of operator's sequence switch contact 306 (80 to 17), and the right-hand back contact and armature of relay 193. This locking circuit is maintained until the relay 193 is energized.

The energization of the relay 193, and of the right-hand winding of relay 91, with which it is connected in parallel from the battery, is effected over a circuit that extends by way of conductor 137 and contact 415 (2 to 9) of the listening-key sequence switch to ground. When the operator listens in on a connecting cord while the operator's sequence switch 300 is standing in position 17, the relay 142 attracts its armatures, in the manner previously described, and then holds them attracted to maintain a flow of current through the left-hand winding of relay 91 until the movement of the listening-key sequence switch into position 2, on its way to the listening-in position 1, supplies a path for current flow through relay 193 and the right-hand winding of the relay 91. Relay 193 is then energized to break the locking circuit of relay 142.

When relay 193 operates, it also completes a circuit which, if the operator's sequence switch is in its 1 position, extends from battery through the motor magnet and contact 302 (1) of the switch, and to ground by way of the right-hand front contact and armature of relay 193. The function of this path is to prevent the operator's sequence switch from remaining in position 1, thus making the operator's position selectable, in case the sequence switch is moved to position 1—by the operation of relay 192, in a manner hereinafter to be explained—at a time when the operator is listening in on a cord circuit and thus is causing the energization of relay 193.

When all of the connecting circuits of an operator's position are in use, with their sequence switches standing in, or moving into or out of, the listening-out position 15, circuits are closed which also serve to make the operator's position unselectable. This result is effected through the medium of a relay 194, the energizing circuit of which extends from battery through the winding of relay, conductor 148, contacts 416 (8 to 18) of the series of listening key sequence

switches associated with the corresponding cord circuits of the position and to ground at the end of the series. When this circuit is completed, the relay 194 is energized and 5 closes a circuit that extends from battery through the right-hand winding of relay 91 and the winding of relay 193 in parallel, conductor 137 and to ground in the front contact and armature of relay 194. Relay 10 91, as the result of the closure of this circuit, prevents the closure of the test control circuit including the relay 92, and, in its right-hand armature and back contact, prevents the closure of the circuit including 15 the relay 192 while the relay 194 continues energized.

While all of the connecting cord circuits of the position are in use, as described above, it will be necessary at times for the operator 20 to listen in on one or another of the cord circuits. In order that her position may continue unselectable while the listening-key sequence switch 400 is moving from the listening-out position 15 to the listening-in position 25 7, the relay 194 is made slow to release. It thus continues to hold the relay 91 energized after its own energizing circuit is broken at position 18 of sequence switch cam 416, and until another path is provided 30 for continuing the energization of relay 91 by way of cam 415 of the listening-key sequence switch when the sequence switch reaches position 2.

As heretofore explained, as soon as the operator's position is selected, the relay 145 is 35 operated to close a circuit that produces a call tone in the operator's telephone receiver. This warns the operator to hold herself in readiness to receive the call that is coming, 40 the connection of the calling line with the operator's telephone being indicated a few moments later (as soon as the cord selector has found an idle cord circuit) by the cessation of the call tone and the lighting of a 45 cord lamp 161. The operator at the moment of selection may be on the point of pressing a listening-in key to listen in on one of the cord circuits. To prevent this, and to hold the operator's position in condition to receive 50 the call, the system is arranged to render all of the listening-in keys inoperative from the instant of selection until the incoming call seizes a cord circuit and the operator's sequence switch has been moved to position 55 17. This is effected by controlling, in the right-hand back contact and armature of relay 95 and in operator's sequence switch contacts 304 (16 $\frac{3}{4}$ to 1), the path over which the listening-in key 191 of any connecting 60 cord circuit applies ground to move its associated sequence switch 400 out of position 15. This path extends from the listening-in key 191 by way of the conductor 130, operator's sequence switch contacts 304 (16 $\frac{3}{4}$ to 1), back 65 contact and right-hand armature of relay 95

and to ground by way of the right-hand front contact and armature of relay 125.

If, after the incoming call has seized the cord circuit and has moved the listening-key sequence switch thereof into the listening-in 70 position 7, in a manner previously described, the operator should find it necessary to supervise an existing connection rather than to receive the order from the calling subscriber, she may do this by pressing the 75 listening-in key 191 of the cord circuit that she wishes to get into communication with. At this time, the operating ground for the listening-in key 191 has been restored by the deenergization of the relay 95 and the movement of the operator's sequence switch cam 304 into its position 17. Therefore, when the listening-in key is pressed, the listening-key sequence switch 400 is moved from position 15 through position 1 and into position 80 7, in a manner already described.

It will be observed that in position 7 of any of the listening-key sequence switches 400, the motor magnet of the switch is connected by way of its cam 402 (7) with a conductor 132 which is also connected with the contact 406 (2 to 6) of each of the other listening-key sequence switches, and thence to ground when any of these contacts is closed. The result of this is that any listening-key sequence switch, in moving from position 2 to position 7, applies a ground to the conductor 132, which serves to move out of the listening-in position 7 any listening-key sequence switch of the associated 90 group that at the time is standing in position 7. Consequently in listening in on the cord circuit of the existing connection, the operator causes the listening key sequence switch of the cord circuit appropriated by 95 the incoming call to be moved out of position 7; and, as the holding relay 152 of that cord circuit is at this time dependent for its continued energization upon the ground by way of contact 407 (2 to 7) of the associated sequence switch, the relay 152 becomes inert, interrupts the circuit of conductor 87, and brings about the restoration of the associated line finder and cord selector switches in the manner heretofore described. 100 The calling line then automatically starts another finder switch and is extended to an operator's connecting circuit in the same way as at first.

After the operator's sequence switch 300 120 has been moved out of position 1, the operator's position is not again selectable until the sequence switch has completed its cycle of rotation and is again standing in position 1. The system is so organized that the interval from the time a position is selected until the position is again made accessible to an incoming call, is controlled by the rate of rotation of the sequence switch, and also by 125 circuits that govern the movement of the 130

switch out of positions 4 and 17, in which positions the switch is adapted under certain circumstances to come to rest. Assuming that the conditions are such that the 5 energizing circuit of the motor magnet of the sequence switch is closed in positions 4 and 17 when the switch reaches those positions, it is necessary that the time required for the switch, moving continuously, to complete its cycle of rotation and return to position 1 shall not be less than the time required for the tripped brushes of the cord selector to move to the terminals of and seize an idle connecting cord circuit and 10 make the operator's position busy by operating the relay 91. Otherwise, the operator's sequence switch cam 304 would reestablish, in position 1, the circuit to the relay 92 before the relay 91 opened that circuit, and 15 would thus make it possible for a second incoming call to select the same position and interfere with the answering of the first call by the operator. One of the functions of the operator's sequence switch is, therefore, to establish a minimum interval within 20 which successive incoming calls may not select the operator's position.

In completing the cycle of its rotation, and reestablishing in position 1 the selectability of the operator's position, the operator's sequence switch is controlled at two points. One of these points is position 4 of the switch, at which point the continued rotation or the stepping of the sequence switch 30 is dependent upon whether or not the operator is at her position, as indicated by the presence or absence of the operator's telephone plug in the telephone jacket 127. The manner in which the control of the sequence switch at this point is effected, 35 through the medium of the relay 125 has already been described.

The movement of the operator's sequence switch out of position 17, aside from the 40 control exercised by the telephone plug and jack through the medium of relay 125, is entirely subject to the control of the relay 192. In other words, after an incoming call has selected the operator's position and has 45 moved the operator's sequence switch to position 17, the sequence switch can be moved out of position 17 and into position 1, to reestablish the selectable condition, only by the energization of the relay 192.

50 The energization of the relay 192 is effected over a path which is closed only when the operator's sequence switches of all of the operators' positions in the group or series are in some position between 2 and 18. In other words, after any operator's position has been selected by an incoming call, that position 55 cannot again be selected by an incoming call as long as the operator's sequence switch of any operator's position of the group is standing in position 1, the call awaiting po-

sition. When all of the operator's sequence switches of the group have been moved out of position 1, either by being selected by an incoming call, or by the operator having listened in on an already-established connection or by the operator having withdrawn her telephone plug from its jack, then a circuit is completed which extends from battery through the winding of the relay 192 of each position, lower switch spring and back contact of the relay, right-hand armature and back contact of relay 91, operator's sequence switch contacts 307 (15 to 18) of the corresponding position, and thence, by way of the common conductor 140, serially through the operator's sequence switch contacts 308 (2 to 18) of all of the sequence switches of the group and the associated conductor 139 to ground at the end of the 60 series.

When this condition occurs, all of the operators' consequence switches standing in position 17 are moved back into the call awaiting position 1, subject, however, to the control in each individual case of the right-hand armature and back contact of the associated relay 91. If at the time the common returning circuit is closed, as described above, the relay 91 of any one of the operators' positions is energized, the sequence switch 300 of that position remains in position 17. Thus the return of any one of the operators' sequence switches to the call-awaiting or accessible position is governed by the condition of the circuits that control the energization of the relay 91 of that operator's position. Consequently, if, when the path to ground of the common conductor 140 is completed by way of the series of cams 308, a particular operator has her listening-in key 191 depressed, or if any of the listening-key sequence switches associated with the cords of that position has its cam 415 in position 2 to 9, or if the contacts of the slow-releasing relay 194 are closed by all of the listening-key sequence switches of the associated cords being in positions 8 to 18, then relay 91 will be energized and the corresponding operator's sequence switch will remain in position 17. The sequence switches 300 of all operators that are not thus engaged at the time are returned to position 1, and those operators' positions are thus made accessible with respect to incoming calls. As a result, the work is uniformly apportioned among the operators and the positions are kept uniformly busy,—a condition which is conducive of the best service both by the operators and by the apparatus.

If, at a time when the operator's sequence switch is in position 17, the operator withdraws her telephone plug from its spring-jack, the operator's sequence switch is moved from position 17 to 4 in a manner already 130

described. To prevent the possibility of a call selecting an idle position and tripping the corresponding set of brushes on the cord selector, as the operator's sequence switch 5 is passing through position 1 on the way to position 4, a circuit is closed on the withdrawal of the plug that extends from battery through the right-hand winding of relay 91, operator's sequence switch contact 10 309 (17 to 14), and ground by way of the right-hand back contact and armature of relay 125. This causes relay 91 to attract its armatures and hold the circuit of relay 92 open as the sequence switch contacts 304 15 are passing through position 1.

The relay 91 also acts in advance of the sequence switch contacts 304 to open the energizing circuit of the relay 92 when the operator presses the listening-in key 191 of 20 any of her cord circuits. The pressing of a key 191 causes the energization of relay 142 to move the sequence switch 300 out of position 1, thus opening the circuit of relay 92 in contact 304 (1); but it also causes the energization of relay 91, which acts instantly 25 to open this same circuit and thus make the position unselectable.

As has heretofore been explained, a calling line, through the cord selector switch of 30 the finder circuit that has seized it, has access to a plurality of operators' positions, and to a plurality of cord circuits at which-ever position is selected. There are as many 35 multiple branches of the finder circuit as there are operators' positions, and each of these branches has a permanent connection with a set of brushes on the cord selector. To prevent the calling line from being extended to a plurality of connecting cord circuits 40 at different positions at the same time, all of these branches are normally held incapable of closure, this being effected by normally holding the brushes of all of the sets untripped so as not to contact with the 45 terminals of the associated groups as the switch moves up. But at the outset of the upward movement of the switch, as previously described, all of the sets of brushes come simultaneously into operable relation 50 with their associated tripping mechanism, and one of the sets is tripped so as to come into engagement with the cord terminals of its associated group, all of the other sets of brushes being held away from their cord 55 circuit terminals. The selection of a particular group of connecting circuits is, therefore, effected by the tripping of a particular set of brushes. The means whereby one set only of the sets of brushes is tripped, and 60 therefore one position only of the positions which may at the time be awaiting a call is selected, will now be described.

As has been explained in a preceding portion of this description, when the sequence 65 switch of an appropriated finder circuit has

reached position 5, it signals, through the medium of relay 55, to all of the operators' positions to signify through the medium of their relays 77 whether or not they are in condition to receive a call. In all of the po-

sitions which are in readiness, the path by way of the winding of relay 92 is closed in the left-hand armature and back contact of relay 91 and in contact 304 (1) of the operator's sequence switch. Therefore, when 75 the relay 55 operates to indicate that a call is to be allotted, the relay 92 of each position that is in readiness to receive a call attracts its armature and operates the relay 77 which corresponds to that operator's posi-

tion and which is associated with the corresponding group of connecting cord terminals on the cord selector frame. The group selecting impulse flows over conductor 73 when the finder sequence switch cam 218 reaches position 6 $\frac{1}{2}$; and this conductor 73 has a branch 141 which passes serially through the armature and back contact of all of the relays 77. Each of the relays, in operating, disconnects the conductor 141 from the next relay 77 in series, and connects it with a path that extends through the associated group relays 94 and 93. Thus, when the selecting impulse passes over conductor 73, it flows through the relays 93 and 94 of 85 the first group in the series that has its relay 77 operated, and is cut off from all of the groups beyond this group in the series. As the setting of the brush tripping mechanism for each group is effected by the energization of the relay 94 of the corresponding group, and as only one relay 94 can be 90 operated at a time, it follows that only one set of brushes can be tripped and only one operator's position selected.

As previously explained, the energization of the relays 93 and 94 is accompanied by the energization of the relay 95 at the associated operator's position, and this relay 100 operates to move the operator's sequence switch out of position 1. This breaks the circuit of the relay 92 in sequence switch contact 304 (1), and the releasing of relay 92 releases the relay 77 of the group circuit. As this happens before the ground is re- 105 moved from the selecting conductor 73, the connection between the conductor 73 and the conductor 141 is controlled in the armature and back contact of the relay 63, which relay is energized as soon as any group relay 94 is operated. This prevents the selecting impulse from being communicated to the relays 93 and 94 of the next group in the series upon the release of the relay 77 of the selected group or position.

To provide an additional safe-guard against the operation of more than one group of selecting relays when conductor 73 is closed, the permanent energizing branch 110 of conductor 73 for the relays 93 and 94 120 is cut off by the action of the relay 63. This 125 prevents the selecting impulse from being communicated to the relays 93 and 94 of the next group in the series upon the release of the relay 77 of the selected group or position.

To provide an additional safe-guard against the operation of more than one group of selecting relays when conductor 73 is closed, the permanent energizing branch 110 of conductor 73 for the relays 93 and 94 130

of the various groups is carried serially through the right-hand armature and back contact of all of the relays 93. Thus, when any relay 93 is operated, the extension of branch 110 necessary for holding energized any relay 93 beyond it in the series is opened, so that even if the opening of the initial energizing path 141 by way of the normal contacts of relay 63 should be delayed, none of the other sets of relays 93 and 94 could be held operated.

The system of this invention is also so arranged as to prevent the selection of the same operator's position by calls simultaneously extended from two different groups of finder switches. The manner in which this is accomplished is shown in Fig. 3 of the drawing. The presence in the organization of a plurality of groups of cord finder or selector switches having access to the same operators' positions and groups of connecting cords, is indicated by the duplication of the group selecting apparatus in "Frame 1" and "Frame 2," and by the multiple connections that are represented as extending from the cord circuit conductors 85, 86, 87 and 88, and from the duplicated set of relays 54, 55, 61 and 63. These connections from the circuits and apparatus of "Frame 1" may be assumed to extend to the finder switches and finder circuits of another group like that illustrated in connection with "Frame 2."

Let it be assumed that the finder sequence switch 200 of one of the finder circuits associated with "Frame 1" is operated so as to close the circuit of conductor 73 of "Frame 1" at exactly the same instant as the conductor 73 of "Frame 2" is closed. Let it also further be assumed that the operator's position 0 is accessible to calls, and that the corresponding relays 77 associated with both frames are therefore energized. The simultaneous closure of the conductor 73 of the two frames simultaneously completes an initial energizing circuit for both sets of relays 93 and 94 corresponding with the 0 operator's position. But relay 93 of "Frame 1," in operating, opens, in its left-hand armature and back contact, the permanent energizing circuit for relays 93 and 94 of this group in "Frame 2." At the same time, the relay 95 of the corresponding operator's position is operated, because its winding is included in the permanent energizing path that relay 93 of "Frame 1" closes through its own winding and that of the associated relay 94. When relay 95 at the 0 position operates, it opens in its left-hand armature and back contact the path over which relays 93 and 94 of both frames are initially energized. Consequently, although the relays 93 and 94 of "Frame 2" may have started to energize when their associated conductor

75 is closed, their initial energizing path is 65 instantly opened in contacts of the relay 95, and their permanent energizing path is opened in the contacts of relay 93 of "Frame 1." Consequently, the operator's position 70 0 is selected by the call that is being extended by the finder circuit of "Frame 1."

As soon as the operator's sequence switch 300 of position 0 has moved out of position 75 1, as a result of the energization of the relay 95, the associated relay 92 is deenergized. This releases the corresponding relays 77 of both frames, and the relay 77 of "Frame 2," in releasing, extends the initial energizing circuit by way of conductor 141 to the selecting relays 93 and 94 of the 80 next group in the series whose relay 77 is energized as a result of the corresponding operator's position being unengaged. Thereupon, the call that is being extended by way of "Frame 2" selects a different operator's position.

In accordance with the present invention, the system disclosed provides means for registering the number of completed calls at each position. When the relay 95 at a position 90 operates as a result of the selection of that position, it closes a circuit that extends from battery through its left-hand armature and front contact, conductor 120, left-hand resting contact and switch spring of 95 relay 195, the winding of this relay, sequence switch contact 310 (13 to 16) and right-hand front contact and armature of relay 125 to ground. Relay 195, in operating, closes a path from battery by way of 100 its left-hand armature and switch spring in substitution of the path first closed in the contacts of the relay 95. The energizing path traced above is held closed in the sequence switch cam 310 until just before 105 the sequence switch 300 reaches position 17. In the meanwhile, the cord finder switch has selected an idle cord and has moved the associated listening key sequence switch 400 into position 7, in a manner already described. Thus, before the path to ground by way of the operator's switch cam 310 is broken, a path for continuing the energization of relay 195 is closed by way of conductor 128 and listening-key sequence 110 switch contact 415 (6 to 7) to ground. If, for any reason, the closure of the last mentioned path should be delayed, the relay 195 is held energized by a path which extends by way of the lower front contacts 115 of the relay 153, conductor 129, calling cord sequence switch contact 502 (1) and inner front contact and armature of relay 151 to ground. This last mentioned path is closed, in a manner previously described, at the instant the connecting circuit is selected, and is held closed until the relays 151, 154 and 120 157 are deenergized by the breaking of their 125

locking circuit in contact 406 (1 to 6) of the listening-key sequence switch. The relay 195 is thus operated the instant the position is selected, and is held operated until its 5 permanent energizing circuit is closed by the movement of the listening-key sequence switch 400 of the selected cord circuit into the listening-in position 7.

When the operator inserts the calling plug 10 170 of the selected connecting cord, thus moving the calling cord sequence switch 500 out of position 1, a circuit is completed that extends from battery through the winding of the peg count register 196, winding of 15 relay 197, right-hand armature and front contact of relay 195, conductor 134, listening-key sequence switch contacts 416 (7) of the connecting circuit over which the connection is being extended, and calling cord 20 sequence switch contact 516 (1 $\frac{3}{4}$ to 3 $\frac{1}{4}$) to ground. The relay 197 closes a locking circuit for itself and the peg count register 196 in its front contact and armature. When the peg count register 196 operates, it closes 25 in its armature and contact a short-circuit of the winding of relay 197, which causes that relay to deenergize and open the locking circuit. In the meanwhile, the movement of the calling cord sequence switch 500 30 has caused the movement of the listening key sequence switch 400 out of position 7, which opens, in contact 415 (6 to 7), the energizing circuit of the relay 195. This permits relay 195 to release and open the 35 path over which the peg count register 196 is operated.

In a preceding portion of this specification, it was stated that if the called subscriber's line was found to be busy, the operator 40 released the connection by pressing her master listening-out key 186. The effect of pressing this key when the listening-key sequence switch 400 is standing in position 7 is to energize the sequence switch and cause 45 it to move to position 15. The circuit for effecting this movement extends from battery through the motor magnet and contact 403 (7) of the listening-key sequence switch and the contacts of the master listening-out 50 key 186 to ground. The called subscriber's line, under the assumption, having been found to be busy, the calling plug 170 has not been inserted, and consequently the calling cord sequence switch 500 has not been 55 moved out of position 1. Therefore, the continued energization of the holding relay 152 is entirely dependent upon the energizing circuit that it has by way of contact 407 (2 to 7) of the listening-key sequence switch. 60 This being the case, the movement of the listening-key sequence switch out of position 7 brings about the deenergization of the holding relay 152, and this, in a manner already described, opens the circuit of the 65 conductor 87 and causes the restoration of the finder circuit switches.

In the system of this invention, the operator is provided with means for preventing the withdrawal of the calling plug 170 from bringing about the automatic release of the 70 connection. This feature is of use, for instance, where the calling subscriber desires to be connected with several other subscribers' lines one after the other. In such a case, the calling subscriber, after having 75 completed his conversation with one subscriber, may signal the operator either by merely remaining at his telephone or by working his switchhook and causing his supervisory lamp 172 to flash. When the 80 operator presses her listening-in key 191 in response to the calling subscriber's signal, she causes the establishment of a circuit, already traced, which moves the listening-key sequence switch into its listening-in position 85 7. In this position, the holding relay 152 has its energizing circuit completed directly to ground by way of the listening-key sequence switch contact 407 (2 to 7). Therefore, the breaking of the path to ground by 90 way of the right-hand front contact and armature of relay 152 and calling cord sequence switch contact 508 (1 $\frac{3}{4}$ to 174), when the calling cord sequence switch is caused to move out of position 17 as a result of the 95 withdrawal of the calling plug 170, the release of the relay 175 and the energization of the relay 157, does not affect the energization of the relay 152, which continues to hold its armatures attracted, thus preventing 100 the restoration of the finder circuit switches.

Provision is made in the system for preventing the mere insertion of the calling plug 170 from exercising any control over 105 the associated apparatus, unless the corresponding connecting cord has been selected by an incoming call and its listening-key sequence switch 400 moved to the listening-in position 7. This is done by including 110 listening-key sequence switch contact 413 (7) in the energizing circuit that is established by the operation of relay 175 upon the insertion of the calling plug 170 to move the calling cord sequence switch 500 out of 115 position 1. This circuit has heretofore been traced. To provide further against the contingency of improperly inserting a calling plug 170 not associated with a connecting circuit over which a connection is being extended, a circuit for the calling supervisory lamp is provided that extends from battery through the resistance 188, lamp 189, left-hand front contact and armature of relay 119, and calling cord sequence switch contact 521 (1) to ground by way of a flashing 120 interrupter 198. This circuit is completed if the relay 119 is actuated by the insertion of 125

the plug 170 at a time when the calling cord sequence switch is in position 1. The flashing of the lamp 189 calls the attention of the operator to the fact that the wrong plug has 5 been inserted.

- When the calling line is one where a charge is made for each call that is successfully completed, the operator, before releasing the connection, presses the charge key 10 176. The pressing of this key completes a circuit that extends from battery through the winding of the relay 156, calling cord sequence switch contacts 509 (17) and upper contact and switch spring of the charge key 15 176 to ground. The relay 156, in attracting its armature, closes a circuit that extends from battery through the winding of the relay 150, contacts of the switch 149 (which are closed in any suitable manner as by a 20 manually operated key when the calling line is a message rate line), armature and inner switch spring of relay 156, left-hand front contact and armature of relay 152, sleeve conductor 87, terminals 117 and corresponding brush 113 of the cord finder switch, conductor 98 of the finder circuit, finder sequence switch contacts 217 (9 $\frac{1}{2}$ to 14) and (12 to 14), right-hand winding of relay 30, 25 finder sequence switch contact 212 (12 $\frac{1}{2}$ to 14), conductor 50, brush 42 and corresponding terminal 46 of the line finder switch, sleeve conductor 53 and through the windings of the connection register 164 to ground. The resistance and electromotive 30 force in the branch of the circuit closed by way of the winding of relay 150, when relay 156 operates, are so proportioned that the current flow over the path traced and through the windings of the connection 35 register 164 is considerably in excess of that which normally flows in this path by way of the branch including the relay 155. As a result, the connection register 164 is operated, and, in operating, short-circuits its 40 right-hand winding. This causes a further increase in the flow of current, which results in the operation of the relatively insensitive relay 150. This relay, in operating, closes a circuit through the lamp 199, and the 45 illumination of that lamp indicates to the operator that the connection register has operated. She then releases the charge key. 50 When the charge key 176 is pressed, it also acts to interrupt, in its lower switch spring and resting contact, a previously traced circuit which is completed in the left-hand back contact and armature of relay 175 when the calling plug is withdrawn, and which serves to energize the relay 157 and move the calling 55 cord sequence switch out of position 17, thus bringing about the release of the connection. The object of this is to prevent starting the releasing operation, and consequently breaking the circuit for the operation 60 of the connection register 164 while the 65

charge key is pressed. The condition which this control of the releasing circuit in the switch spring and contact of the charging key is adapted to prevent, is one which may arise in case the operator withdraws the 70 connecting plug and presses the charge key at about the same time.

Certain of the features that are shown and described in the complete organization herein disclosed are not claimed herein, but are 75 made the subject of claims in other copending applications.

What is claimed is:

1. The combination with an operator's position provided with a plurality of connecting circuits, of means for extending a connection to said operator's position, said means being adapted first to select the operator's position and then to select one of said connecting circuits, an electromagnetic 80 switch actuated in the selection of the operator's position, a connection switch for each of said connecting circuits, said switch being closed in extending a connection by means of the associated connecting circuit, a 85 registering device, and means for actuating the same made operative in the operation of said electromagnetic switch and the closure of any one of said connection switches. 90

2. The combination with an operator's position having a plurality of connecting circuits each terminating in a connection switch, of means for extending connections to said position, operator's telephone apparatus, a listening switch for each connecting circuit adapted when operated to connect the operator's telephone apparatus with the associated circuit, an electromagnetic registering device, an energizing path therefor, a relay for closing said energizing path 100 at one point, said relay being made operative by the extending of a call to said position and the closure of any one of said listening switches, and means actuated in the closure of any one of said connection switches for completing the circuit of said energizing path. 105

3. In a telephone system, the combination with a connecting circuit, of a calling line and a called line united thereby, service 110 charging apparatus associated with said calling line, a key for operating the same associated with said connecting circuit, means for automatically disconnecting the connecting circuit from the calling line, and means actuated in operating said charging key for preventing the operation of said automatic disconnecting means. 115

4. In a telephone system, the combination with a connecting circuit, of a calling line and a called line united thereby, electromagnetic apparatus associated with said calling line, a switch for operating the same associated with said connecting circuit, means for automatically disconnecting the connect- 125 130

ing circuit from the calling line made operative in disconnecting the connecting circuit from the called line, and means actuated in operating said key to prevent the operation 5 of said automatic disconnecting means.

5. The combination with a connecting circuit, of a telephone line, an automatic switch operated to extend said line to said connecting circuit, a toll device associated with 10 said line, a switch associated with said connecting circuit, and means actuated upon the operation of said switch for operating said toll device and preventing the restoration of said automatic switch.

15 6. The combination with a connecting circuit, of a telephone line, automatic switching mechanism for extending said line to said connecting circuit, a holding circuit for

said automatic switching mechanism operating to hold said telephone line in connection 20 with said connecting circuit as long as current flows through said holding circuit, a connection register associated with said line and having its operating magnet included in said holding circuit, a register key associated 25 with said connecting circuit, means actuated upon the operation of said key for changing the current flow in said holding circuit to operate said connection register and hold said connection while said key is operated, 30 and means operable to interrupt the flow of current in said holding circuit to release said connection when said key is restored.

In witness whereof I hereunto subscribe my name this 9th day of April, A. D. 1919. 35

SAMUEL B. WILLIAMS, JR.
